ELECTRIC-WAVE FILTER

Wilhelm Cauer, Gottingen, Germany

Application December 6, 1930, Serial No. 500,595
In Germany June 8, 1928

73 Claims. (Cl. 178—44)

My invention relates to electric-wave filters, and more particularly to filters adapted for the selection and propagation of electromagnetic signals of prescribed ranges of frequency. From a more limited aspect, the invention relates to symmetrical wave filters, as well as to such unsymmetrical filters as are equivalent to a symmetrical filter connected in series with a transformer, or with a phase-correction circuit, or both.

One of the objects of this invention is to provide new and improved electric-wave filters, some of them of new types, never before known, and others, also new, but having certain features of equivalency with known filters.

A second object is to provide new and improved electric-wave-filter circuits that shall have the property that the image impedance in the transmission bands shall be substantially constant to any required degree of accuracy.

A further object is to improve the behavior of the working or total attenuation of filter networks.

Another object is to provide a new and improved wave filter that, when connected with a long line, shall reduce the echo or reflection effect to a value as small as may be desired.

It is further an object of my invention to improve upon filters of types already known, to the ends that their efficiency may be improved, their cost of manufacture lessened, and the number of elements, of which they are composed, reduced.

Other and still further objects will be explained hereinafter, and will be particularly pointed out in the appended claims, it being understood that I intend, by suitable expressions in the claims, to specify all the novelty that the invention may possess.

The invention will now be explained in connection with the accompanying drawings, in which Fig. 1 is a diagrammatic view illustrating a four-terminal, symmetrical filter embodying the present invention, the filter being shown in Wheatstone-bridge-network form; Fig. 2 is a similar view illustrating circuit elements that may be embodied in the circuit connections of Fig. 1; Fig. 3 is a diagrammatic view of an unsymmetrical filter circuit arranged according to one general form of the present invention; Fig. 4 is a corresponding view of a symmetrical filter circuit according to my invention, this circuit also being of quite general form; Figs. 5 and 6 are diagrammatic views of prior-art filters for comparison purposes; Figs. 7 to 12 are diagrammatic views of filter circuits built according to the present invention; Figs. 13 and 14 are similar views of known filter circuits for comparison purposes; Fig. 15 is a diagram showing plots or curves of image-impedance characteristics of my filter circuits; and Fig. 16 is a similar diagram showing plots or curves of corresponding attenuation characteristics.

In Fig. 2, there are shown two networks, each having only one pair of terminals 1, 1. In Figs. 1 and 3 to 14, there are shown four-terminal networks, one pair of the terminals at 1, 1 or 1, 1' and the other pair at 2, 2 or 2, 2'. One of these two pair may be the input terminals and the other pair the output terminals.

Two networks are said to be equivalent when they have the same exterior efficiency characteristics as functions of frequency, irrespective of what might happen interiorly. In the case of equivalent, two-terminal networks, all their exterior properties can be expressed by the driving-point impedance function z . The function z will be referred to as the frequency characteristic of a two-terminal network. Four-terminal networks are determined by three such independent functions of frequency; or, if desired, there are four such functions, A, B, C and D, of which three only are independent. Two four-terminal networks are equivalent, therefore, if they have the same frequency-characteristic functions A, B, C and D. A complete set of such functions may be obtained, for example, in the following manner:

Letting E_1 represent the complex voltage at the input terminals 1, 1; I_1 represent the complex current at the input terminals 1, 1; E_2 represent the complex voltage at the output terminals 2, 2; and I_2 represent the complex current at the output terminals 2, 2; then there are two linear equations between these voltages and currents, as follows:

$$E_1 = AE_2 + BI_2$$

$$I_1 = CE_2 + DI_2$$

where

$$\begin{vmatrix} A & B \\ C & D \end{vmatrix} = 1$$

Then A, B, C and D are the said functions of frequency, and will be referred to as the frequency characteristics of a four-terminal network.

A four-terminal network is said to be symmetrical when its exterior properties remain unchanged upon interchanging the input terminals 1, 1 and the output terminals 2, 2. In the symmetrical case, all characteristic properties are determined by only two functions of frequency, as

$$A = D$$

A circuit is a canonical circuit for a certain kind of network if it can be made equivalent to all circuits of this kind by suitable choice of the size of its elements.

The circuit of Fig. 1 is a canonical, symmetrical, four-terminal network, as is proved in my paper entitled, "Über die Variabeln eines passiven Vierpolen" in Sitzungsberichte der Preussischen Akademie den Wissenschaften, 1927, the said two independent frequency characteristics being in-

dicated at z_1 and z_2 , respectively, in the pairs of opposite arms of a Wheatstone bridge. These functions z_1, z_2 are always physically realizable driving-point impedances. In the cases where 5 the resistances are zero, one possible canonical form of z_1 and z_2 is illustrated in Fig. 2.

The circuit of Fig. 3 is one example of a canonical, unsymmetrical, four-terminal network without resistances. The circuit of Fig. 3, 10 by suitable choice of the elements, can be made equivalent to a combination of a symmetrical wave filter in series with a tightly-coupled transformer T or a phase-correction network, or both.

It will conduce to clearness not to enter into 15 long-drawn-out mathematical proofs here, but to state concisely the general steps of the mathematical treatment, and the results obtained thereby. Some of the proofs will be found in several of my publications, as follows:

20 "Vierpole", Elektrische Nachrichtentechnik, vol. VI, p. 272, 1929.

"Über eine Klasse von Funktionen, die die Stieltjesschen Kettenbrüche als Sonderfall enthält", Jahresbericht der deutschen Mathematikervereinigung, 1929, vol. 38, page 63.

"Untersuchungen über ein Problem, das drei positiv definite quadratische Formen mit Streckenkomplexen in Beziehung setzt", Mathematische Annalen, Band 105, Heft 1, 1931.

30 "Die Siebschaltungen der Fernmeldeotechnik", Zeitschrift für angewandte Mathematik und Mechanik, October, 1930.

See also: "Siebschaltungen", V. D. I. Verlag, Berlin, 1931.

35 The impedances z_1 and z_2 are rational functions of the frequency f , to be evaluated according the requirements of the particular problem in hand. It is convenient to deal, not with these functions themselves, but with their ratio,

40
$$\frac{z_2}{z_1}$$

and their product, $z_1 z_2$, which, naturally, are also rational functions of the frequency f . The 45 reasons for this will appear from the following considerations:

The propagation constant is usually represented by the symbol Γ , and its real part, which is the attenuation constant, will be represented by 50 A₁. Γ depends on

55
$$\frac{z_2}{z_1}$$

only, according to the following equation, in which e represents the Naperian base of logarithms:

$$60 e^{\Gamma} = \frac{\sqrt{z_2} + 1}{\sqrt{z_2} - 1}$$

The image impedance Z may be determined by the equation

$$Z = \sqrt{z_1 z_2}$$

65 The wave-filter circuit will be most efficient when the following conditions are most nearly met: In the attenuation regions,

$$70 \frac{z_2}{z_1} = 1$$

and in the transmission bands,

$$z_1 z_2 = R^2$$

where R is a constant and equal to the impedance 75 of the given sending or receiving apparatus. It

will be understood, of course, that these two equations are never actually satisfied, in practice. As before stated, the more nearly they are satisfied, the better will be the efficiency of the filter.

These requirements correspond to infinite attenuation in the attenuation bands and zero attenuation in the transmitting bands. To make a good approximation to zero attenuation in the transmitting bands, it is necessary that the resistances be nearly zero. In the following portion of this specification, the resistances will be wholly neglected for this reason and also because it will simplify the discussion without in reality detracting from the generality of the method.

In addition to the above requirements for

$$\frac{z_2}{z_1}$$

$$z_1 z_2$$

and $z_1 z_2$ for attenuation, it may be noted that 20 the requirement $z_1 z_2 = R^2$ serves to reduce the echo effect when the filter is connected with a long line having the characteristic impedance R .

There are many different types of symmetrical wave filters and all of these may be designed from 25 my formulas. The most simple types may however, be reduced to four: band-pass filters; low-and-high-pass filters; low-pass filters; and high-pass filters.

All possible wave filters of all four of these 30 types may be obtained by using the following tables, except that in the case of classes a, b, c . . ., only those classes are represented by the formulas in which the total number of zeros and poles is symmetrical on the two sides of the critical or cut-off frequencies ω_{-1} and ω_1 , as such classes only may be expected to be of importance, in practice. The frequencies ω_{-1} and ω_1 may be defined as the frequencies separating attenuation from transmitting bands, and may be 40 measured in radians per second. It will be understood that ω_{-1} and ω_1 represent particular, cut-off frequency values, and that, in general,

$$\omega = 2\pi f$$

and $\lambda = j\omega$ 45

j representing the imaginary

$$\sqrt{-1}$$

The ω 's with subscripts appear in these tables 50 in their natural order of magnitude from left to right. For example, the resonance or the anti-resonance frequencies of the impedances z_1 and z_2 appearing in the tables for class 6 are

$$\omega_{-1}, \omega_{-a}, \omega_{-b}, \omega_0, \omega_b, \omega_a, \omega_1$$

where 55

$$\omega_{-1} < \omega_{-a} < \omega_{-b} < \omega_0 < \omega_b < \omega_a < \omega_1$$

All these ω 's are arbitrary constants. The only other symbols appearing in these tables, m and μ , represent also arbitrary constants which are positive. In Table II, α_3 is identical with c , α_4 with d , etc. In Table IV, α_3 is identical with γ , α_4 with δ etc.

With further reference to these tables, it will 65 be understood that filters designated according to my notation will have their attenuation characteristic given first, and their image-impedance characteristic second. Thus, as to be observed, a filter of class 3d is a band-pass filter of attenuation characteristic class 3 and image-impedance characteristic class d. Similarly, a filter of class 70 d3 is a low-and-high-pass filter of attenuation characteristic d and image-impedance characteristic 3.

Table I

The following formulas represent:

$$\sqrt{\frac{z_2}{z_1}}$$

for a band-pass filter;

$$\sqrt{\frac{z_1 z_2}{z_1 z_2}}$$

10 for a low-and-high-pass filter.

$$(1) m \frac{\sqrt{\lambda^2 + \omega_{-1}^2}}{\sqrt{\lambda^2 + \omega_1^2}}$$

$$(2) m \frac{\lambda^2 + \omega_0^2}{\sqrt{\lambda^2 + \omega_{-1}^2} \sqrt{\lambda^2 + \omega_1^2}}$$

$$(3) m \frac{\sqrt{\lambda^2 + \omega_{-1}^2} (\lambda^2 + \omega_a^2)}{(\lambda^2 + \omega_{-a}^2) \sqrt{\lambda^2 + \omega_1^2}}$$

$$(4) m \frac{(\lambda^2 + \omega_{-a}^2) (\lambda^2 + \omega_a^2)}{\sqrt{\lambda^2 + \omega_{-1}^2} (\lambda^2 + \omega_0^2) \sqrt{\lambda^2 + \omega_1^2}}$$

$$(5) m \frac{\sqrt{\lambda^2 + \omega_{-1}^2} (\lambda^2 + \omega_{-b}^2) (\lambda^2 + \omega_b^2)}{(\lambda^2 + \omega_{-a}^2) (\lambda^2 + \omega_b^2) \sqrt{\lambda^2 + \omega_1^2}}$$

$$(6) m \frac{(\lambda^2 + \omega_{-a}^2) (\lambda^2 + \omega_b^2) (\lambda^2 + \omega_a^2)}{\sqrt{\lambda^2 + \omega_{-1}^2} (\lambda^2 + \omega_{-b}^2) (\lambda^2 + \omega_b^2) \sqrt{\lambda^2 + \omega_1^2}}$$

$$\dots$$

$$(30) (2n-1) m \frac{\sqrt{\lambda^2 + \omega_{-1}^2} (\lambda^2 + \omega_{a,1}^2) (\lambda^2 + \omega_{a,2}^2) \dots (\lambda^2 + \omega_{a,2n-2}^2)}{(\lambda^2 + \omega_{a,1}^2) (\lambda^2 + \omega_{a,3}^2) \dots (\lambda^2 + \omega_{a,2n-2}^2) \sqrt{\lambda^2 + \omega_1^2}}$$

$$(2n) m \frac{(\lambda^2 + \omega_{a,1}^2) (\lambda^2 + \omega_{a,2}^2) \dots (\lambda^2 + \omega_{a,2n-2}^2)}{\sqrt{\lambda^2 + \omega_{-1}^2} (\lambda^2 + \omega_{a,2}^2) \dots (\lambda^2 + \omega_{a,2n-2}^2) \sqrt{\lambda^2 + \omega_1^2}}$$

$$\dots$$

$$\dots$$

$$(2n-1) m \frac{\lambda (\lambda^2 + \omega_{a,2n-3}^2) (\lambda^2 + \omega_{a,2n-5}^2) \dots (\lambda^2 + \omega_{a,1}^2)}{(\lambda^2 + \omega_{a,2n-2}^2) (\lambda^2 + \omega_{a,2n-4}^2) \dots (\lambda^2 + \omega_{a,2}^2) \sqrt{\lambda^2 + \omega_1^2}}$$

$$(2n) m \frac{(\lambda^2 + \omega_{a,2n-1}^2) (\lambda^2 + \omega_{a,2n-3}^2) \dots (\lambda^2 + \omega_{a,1}^2)}{\lambda (\lambda^2 + \omega_{a,2n-2}^2) \dots (\lambda^2 + \omega_{a,2}^2) \sqrt{\lambda^2 + \omega_1^2}}$$

$$\dots$$

$$\dots$$

$$\dots$$

$$\dots$$

Table II

The following formulas represent:

$$\sqrt{\frac{z_1 z_2}{z_1}}$$

45 for a band-pass filter;

$$\sqrt{\frac{z_2}{z_1}}$$

for a low-and-high-pass filter.

$$(a) \mu \frac{\sqrt{\lambda^2 + \omega_{-1}^2}}{\lambda \sqrt{\lambda^2 + \omega_1^2}}$$

$$(b) \mu \frac{\lambda}{\sqrt{(\lambda^2 + \omega_{-1}^2) (\lambda^2 + \omega_1^2)}}$$

$$(c) \mu \frac{\lambda \sqrt{\lambda^2 + \omega_{-1}^2} (\lambda^2 + \omega_a^2)}{(\lambda^2 + \omega_{-a}^2) \sqrt{\lambda^2 + \omega_1^2}}$$

$$(d) \mu \frac{(\lambda^2 + \omega_{-a}^2) (\lambda^2 + \omega_a^2)}{\lambda \sqrt{(\lambda^2 + \omega_{-1}^2) (\lambda^2 + \omega_1^2)}}$$

$$(e) \mu \frac{(\lambda^2 + \omega_{-b}^2) \sqrt{\lambda^2 + \omega_{-1}^2} (\lambda^2 + \omega_b^2)}{\lambda (\lambda^2 + \omega_{-a}^2) \sqrt{\lambda^2 + \omega_1^2} (\lambda^2 + \omega_b^2)}$$

$$(f) \mu \frac{\lambda (\lambda^2 + \omega_{-a}^2) (\lambda^2 + \omega_a^2)}{(\lambda^2 + \omega_{-b}^2) \sqrt{(\lambda^2 + \omega_{-1}^2) (\lambda^2 + \omega_1^2) (\lambda^2 + \omega_b^2)}}$$

$$\dots$$

$$(2n-1) \mu \frac{(\lambda^2 + \omega_{a,n-1}^2) (\lambda^2 + \omega_{-a,n-3}^2) \dots (\lambda^2 + \omega_{-a,1}^2) \sqrt{\lambda^2 + \omega_{-1}^2} (\lambda^2 + \omega_{a,1}^2) \dots (\lambda^2 + \omega_{a,n-2}^2)}{\lambda (\lambda^2 + \omega_{-a,n-2}^2) (\lambda^2 + \omega_{-a,n-4}^2) \dots (\lambda^2 + \omega_{-a,2}^2) \sqrt{\lambda^2 + \omega_1^2} (\lambda^2 + \omega_{a,2}^2) \dots (\lambda^2 + \omega_{a,n-1}^2)}$$

$$(2n) \mu \frac{\lambda (\lambda^2 + \omega_{-a,n-2}^2) \dots (\lambda^2 + \omega_{-a,1}^2) (\lambda^2 + \omega_{a,1}^2) \dots (\lambda^2 + \omega_{a,n-1}^2)}{(\lambda^2 + \omega_{-a,n-1}^2) \dots (\lambda^2 + \omega_{-a,3}^2) \sqrt{(\lambda^2 + \omega_{-1}^2) (\lambda^2 + \omega_1^2) (\lambda^2 + \omega_{a,2}^2) \dots (\lambda^2 + \omega_{a,n-1}^2)}}$$

$$\dots$$

where $v=n$ for n odd, $v=n+1$, $\omega_{-a,n}=0$ and the last factor of the denominator is omitted for n even.

Table III

The following formulas represent:

$$\sqrt{\frac{z_2}{z_1}}$$

for a low-pass filter;

$$\sqrt{\frac{z_1 z_2}{z_1}}$$

for a high-pass filter.

$$(1) m \frac{\lambda}{\sqrt{\lambda^2 + \omega_1^2}}$$

$$(2) m \frac{\lambda^2 + \omega_a^2}{\sqrt{\lambda^2 + \omega_1^2}}$$

$$(3) m \frac{\lambda (\lambda^2 + \omega_a^2)}{(\lambda^2 + \omega_b^2) \sqrt{\lambda^2 + \omega_1^2}}$$

$$(4) m \frac{(\lambda^2 + \omega_b^2) (\lambda^2 + \omega_a^2)}{\lambda (\lambda^2 + \omega_b^2) \sqrt{\lambda^2 + \omega_1^2}}$$

$$(5) m \frac{\lambda (\lambda^2 + \omega_c^2) (\lambda^2 + \omega_a^2)}{(\lambda^2 + \omega_d^2) (\lambda^2 + \omega_b^2) \sqrt{\lambda^2 + \omega_1^2}}$$

$$(6) m \frac{\lambda^2 + \omega_c^2) (\lambda^2 + \omega_b^2) (\lambda^2 + \omega_a^2)}{\lambda (\lambda^2 + \omega_d^2) (\lambda^2 + \omega_b^2) \sqrt{\lambda^2 + \omega_1^2}}$$

Table IV

The following formulas represent:

$$\sqrt{\frac{z_1 z_2}{z_2}}$$

for a low-pass filter;

$$\sqrt{\frac{z_2}{z_1}}$$

for a high-pass filter.

$$(a) \mu \frac{1}{\sqrt{\lambda^2 + \omega_1^2}}$$

$$(b) \mu \frac{(\lambda^2 + \omega_a^2)}{\sqrt{\lambda^2 + \omega_1^2}}$$

$$(c) \mu \frac{(\lambda^2 + \omega_a^2) (\lambda^2 + \omega_b^2)}{\sqrt{\lambda^2 + \omega_1^2} (\lambda^2 + \omega_b^2)}$$

$$(d) \mu \frac{(\lambda^2 + \omega_a^2) (\lambda^2 + \omega_c^2)}{\sqrt{\lambda^2 + \omega_1^2} (\lambda^2 + \omega_c^2)}$$

$$(e) \mu \frac{(\lambda^2 + \omega_a^2) (\lambda^2 + \omega_c^2)}{\sqrt{\lambda^2 + \omega_1^2} (\lambda^2 + \omega_b^2) (\lambda^2 + \omega_c^2)}$$

55

60

65

70

75

$$(5) \mu \frac{(\lambda^2 + \omega_a^2)(\lambda^2 + \omega_{-a}^2)(\lambda^2 + \omega_1^2)}{\sqrt{\lambda^2 + \omega_1^2}(\lambda^2 + \omega_a^2)(\lambda^2 + \omega_{-a}^2)}$$

5

$$(\alpha_{2n-1}) \mu \frac{(\lambda^2 + \omega_{a,1}^2)(\lambda^2 + \omega_{a,3}^2) \dots (\lambda^2 + \omega_{a,2n-2}^2)}{\sqrt{\lambda^2 + \omega_1^2}(\lambda^2 + \omega_{a,2}^2)(\lambda^2 + \omega_{a,4}^2) \dots (\lambda^2 + \omega_{a,2n-2}^2)}$$

10

$$(\alpha_{2n}) \mu \frac{(\lambda^2 + \omega_{a,1}^2)(\lambda^2 + \omega_{a,3}^2) \dots (\lambda^2 + \omega_{a,2n-1}^2)}{\sqrt{\lambda^2 + \omega_1^2}(\lambda^2 + \omega_{a,2}^2) \dots (\lambda^2 + \omega_{a,2n-2}^2)}$$

It will be noted that, according to this classification of filter networks, the higher the classification number of the filter circuit, the greater is the number of circuit elements that it contains.

In using these tables, one must first decide which of these four types of filters to design. If, for example, it is to be a band-pass filter, Table I will supply the value of the attenuation characteristic

$$\sqrt{\frac{z_2}{z_1}}$$

for any of the desired classes 1, 2, 3 . . . Table II will similarly supply the corresponding value of the image-impedance characteristics

$$\sqrt{z_1 z_2}$$

30 for any of the desired classes $a, b, \dots$, these letters representing any whole number. These same values will correspond to

$$\sqrt{z_1 z_2}$$

and

$$\sqrt{\frac{z_2}{z_1}}$$

respectively, for a low-and-high-pass filter. Tables III and IV will similarly respectively furnish the values of

$$\sqrt{\frac{z_2}{z_1}}$$

and

$$\sqrt{z_1 z_2}$$

45 for a low-pass filter and

$$\sqrt{\frac{z_2}{z_1}}$$

and

$$\sqrt{\frac{z_1}{z_2}}$$

50 for a high-pass filter. Thus, given the product and the quotient, it is possible to compute the quantities themselves, z_1 and z_2 .

55 For example, as already stated, class $3d$ represents a band-pass filter with attenuation characteristic class 3 and image-impedance characteristic class d . To evaluate this filter, the following value is taken from Table I, for a band-pass filter, for class 3:

$$\sqrt{\frac{z_2}{z_1}} = m \frac{\sqrt{\lambda^2 + \omega_{-1}^2}(\lambda^2 + \omega_a^2)}{(\lambda^2 + \omega_{-a}^2)\sqrt{\lambda^2 + \omega_1^2}}$$

60 and from Table II, for class d , the following is taken:

$$\sqrt{z_1 z_2} = \mu \frac{(\lambda^2 + \omega_{-a}^2)(\lambda^2 + \omega_a^2)}{\lambda \sqrt{(\lambda^2 + \omega_{-1}^2)(\lambda^2 + \omega_1^2)}}$$

70 Now,

$$z_1 = \sqrt{z_1 z_2} + \sqrt{\frac{z_2}{z_1}}$$

and

$$z_2 = \sqrt{z_1 z_2} - \sqrt{\frac{z_2}{z_1}}$$

75

Hence, for class $3d$,

$$z_1 = \frac{\mu (\lambda^2 + \omega_{-a}^2)(\lambda^2 + \omega_a^2)(\lambda^2 + \omega_1^2)}{m \lambda (\lambda^2 + \omega_{-1}^2)(\lambda^2 + \omega_a^2)}$$

and

$$z_2 = \frac{m \mu (\lambda^2 + \omega_{-a}^2)(\lambda^2 + \omega_a^2)(\lambda^2 + \omega_1^2)}{\lambda (\lambda^2 + \omega_{-1}^2)(\lambda^2 + \omega_1^2)}$$

Corresponding to each four-terminal network represented by the classes thus obtained, there exists an inverse or reciprocal four-terminal network, as defined, for example, on page 281 of a paper entitled "Vierpole", in Elektrische Nachrichtentechnik for 1929. The inverse four-terminal network is a net-work for which the frequency characteristics

$$\sqrt{z_1 z_2}$$

and

$$\sqrt{\frac{z_2}{z_1}}$$

are respectively the reciprocals of the corresponding frequency characteristics

$$\sqrt{z_1 z_2}$$

and

$$\sqrt{\frac{z_1}{z_2}}$$

for the original net-work. Each inverse or reciprocal filter network is, therefore, a filter of the same type as that of which it is the reciprocal. It is not necessary to compute tables for the designing of these reciprocal networks as they may be obtained from the same Tables I to IV merely by using the reciprocals of the values therein tabulated.

The reciprocal filter, is, therefore, designated herein and in the above tables in the same way as the filter of which it is the reciprocal, but with an added asterisk. Thus, a filter of class $3d^*$ will represent a band-pass filter which is the reciprocal of a filter of class $3d$. To evaluate the band-pass filter of class $3d^*$, the reciprocal of the value for

$$\frac{z_2}{z_1}$$

will be taken, for class 3, as the value of

$$\frac{z_1}{z_2}$$

thus:

$$\sqrt{\frac{z_1}{z_2}} = \frac{(\lambda^2 + \omega_{-a}^2)\sqrt{\lambda^2 + \omega_1^2}}{m \sqrt{(\lambda^2 + \omega_{-1}^2)(\lambda^2 + \omega_a^2)}}$$

From Table II, similarly, for class d , the following reciprocal is taken:

$$\sqrt{\frac{z_2}{z_1}} = \frac{\lambda \sqrt{(\lambda^2 + \omega_{-1}^2)(\lambda^2 + \omega_1^2)}}{\mu (\lambda^2 + \omega_{-a}^2)(\lambda^2 + \omega_a^2)}$$

and the values of z_1 and z_2 will, of course, be found to be the reciprocals of those deduced above for class $3d$.

As the absolute value of the logarithm of a number is the same as the absolute value of the logarithm of the reciprocal of the number,

$$\left| \log \sqrt{\frac{z_2}{z_1}} \right| = \left| \log \sqrt{\frac{z_1}{z_2}} \right|$$

70 The two equal expressions above for

$$\sqrt{\frac{z_2}{z_1}}$$

5

10

15

20

30

35

40

45

50

55

60

75

and its reciprocal may, therefore, be combined into one expression, as follows:

$$5 \quad \log \sqrt{\frac{z_2}{z_1}} = \log m \frac{\sqrt{\lambda^2 + \omega_{-1}^2}(\lambda^2 + \omega_1^2)}{(\lambda^2 + \omega_{-1}^2)\sqrt{\lambda^2 + \omega_1^2}}$$

Condensed expressions of this character covering a class and its reciprocal will be used in claims 1 to 10 inclusive, and other claims.

10 As I have shown in my publications, every possible symmetrical four-terminal filter network, whether or not heretofore known in the art, belongs to one or another of these classes. The values of z_1 and z_2 corresponding to every such 15 network may be computed. See, for example, the explanations given in my above-mentioned paper, entitled "Vierpole". Conversely, knowing the values of z_1 and z_2 corresponding to any given network, it is possible to compute their product 20 and their ratio, and thus to fix the class to which such network belongs.

It follows, of course, that some of the networks obtained from Tables I to IV are already known in the art. Most of these networks, however, and particularly most of those obtained from the image-impedance classes, are original with me. Even in those cases, however, where the networks are already known, except in the very lowest classes, my invention has a further advantage 30 in that the arbitrary parameters m , μ and the various ω 's may be so chosen as to produce the most efficient results. Heretofore, these known networks have been designed in haphazard fashion, and the results obtained thereby have depended more or less on chance. According to my invention, it is possible to compute beforehand those values of the parameters that shall yield the maximum efficiency in any network, new or old. Old filters, therefore, may be so 40 designed as to fulfil the requirements imposed on them more accurately than has been possible heretofore. Another advantage of my invention, applicable both to old and to new networks, but particularly advantageous, for present purposes, 45 in connection with the old networks, is that it is possible to reduce the number of circuit elements that may be employed, thus lessening the cost of production of the network circuits.

With regard, first, to the choice of the best 50 parameters, the labor attendant upon this work may be shortened by graphically using an extensive collection of curves, published in the above paper "Siebschaltungen". These curves take into account not only the capacities and the inductances, but the resistances, as well. For simplicity, the method of treatment will be explained in connection with a concrete example, but it will be understood that the method is perfectly general. Parameters defining resonances and anti-resonances and being proportioned to provide a free 60 transmission band are advantageous if they are spaced in the attenuation range remote from the band limit or band limits on a progressively closer scale near to the band limit to provide substantially uniform characteristic impedance (image impedance) throughout the band.

Let it, then, be assumed that it is desired to obtain z_1 and z_2 with the most satisfactory parameters for a band-pass filter having a narrow 70 transmission band; that is,

$$\frac{\omega_1 - \omega_{-1}}{\omega_{-1} + \omega_1} \ll 1$$

75 Reference may now be had to Figs. 15 and 16.

which contain plots or curves of image-impedance and attenuation constants with the best parameters. In these figures, the abscissa is taken, not as the pulsatance ω , but as the normalized frequency Ω , where

$$\Omega = \frac{2\omega - (\omega_{-1} + \omega_1)}{\omega_1 - \omega_{-1}}$$

This is a mere matter of convenience, as it introduces symmetry, and the cut-off frequencies 10 are determined by

$$\Omega = \pm 1$$

The scale of ordinates for the image-impedance or surge-impedance curves, Fig. 15, is logarithmic, and is so chosen that the constant to which $z_1 z_2$ approximates is unity. All cases may easily be reduced to this case by dividing the values of z_1 and z_2 necessary for the particular filter desired by the previously given or known value of R of the transmitting or receiving apparatus. In the following discussion, and also in the Tschebyscheff formulas hereinafter given, z_1 and z_2 will be assumed to have been so reduced so as to have the following values:

$$z_1 = \frac{Z_1}{R} \text{ and } z_2 = \frac{Z_2}{R}$$

For filters having comparatively narrow transmission bands, it is possible to choose image-impedance and attenuation characteristics that are symmetrical with respect to both cut-off frequencies ω_1 and ω_{-1} , that is, where

$$\Omega = \pm 1$$

and only such characteristics are, therefore, embodied in the curves of Figs. 15 and 16. It is possible to apply corrections so as to have the same curves applicable to all filter circuits. The image impedances in the odd classes $a, c, e, \dots$ etc. assume reciprocal values when for Ω is substituted its negative, $-\Omega$. All the other characteristics are converted by this substitution into their images about the line $\Omega=0$, as an axis of reflection. These considerations make it possible greatly to simplify the showing of these curves.

In Fig. 15, there are shown image-impedance curves c, d, e and f . The ordinate

$$\sqrt{z_1 z_2}$$

is on a logarithmic scale, but the abscissa, representing Ω , is on a natural scale. These curves c, d, e and f are so chosen that they have in this logarithmic scale the minimum deflection from the straight line

$$\sqrt{z_1 z_2} = 1$$

in the interval

$$-\kappa < \Omega < \kappa$$

This is called "approximation in the Tschebyscheff sense" and is effected by making equal the deviation at these points of maximum deviation. Over this range, max

$$\log \sqrt{z_1 z_2}$$

is a minimum, or log

$$\sqrt{z_1 z_2}$$

over the range $-\kappa < \Omega < \kappa$ approximates to zero in the Tschebyscheff sense. In the particular case

75

- illustrated, in Fig. 15 the boundary values for Ω , defining the range, are $+\kappa=0.95$ and $-\kappa=-0.95$. The boundary value $\kappa=0.95$ is shown on the drawings, but the boundary value $-\kappa=-0.95$ is not illustrated, as it is the reflection, about the line $\Omega=0$, of the boundary value $\kappa=0.95$, as before explained. It will be understood that these curves and these boundary limits are chosen for illustrative purposes only, as it is possible to have 10 an arbitrary boundary limit κ , with the only restriction that

$$0 < \kappa < 1$$

- 15 The boundary limit κ may be taken as close to unity as desired, but it can not equal unity, this value unity being the limiting cut-off frequency of the transmission band.

As inspection of these curves *c*, *d*, *e* and *f* will demonstrate, their maxima and minima occur alternately between the boundary limits 20

$$\Omega = \pm \kappa = \pm 0.95$$

- 25 with maximum or minimum at these limits if the passage through the value of maximum deviation be considered as a maximum or minimum. For example, the curve *f* has three minima and two maxima in the interior of the interval and two maxima at the boundaries. Two of these 30 three minima are indicated at F_1 and F_2 , the third being a reflection, about the straight line $\Omega=0$, of the minimum F_1 . One of the two interior maxima is shown at F_3 , the other being similarly a reflection thereof. One of the two boundary maxima is indicated at F_4 , the other being likewise a reflection thereof.

The curves oscillate between two straight lines which are parallel to the line

$$40 \quad \log \sqrt{z_1 z_2} = 0$$

- and both of which are distant from this line by the same amount, $\log H$, defined hereinafter, and on both sides of it. For example, for the curve *f*, the two straight lines are indicated at f_1 and f_2 , where H is the maximum value of the reduced 45 surge impedance

$$\sqrt{z_1 z_2}$$

- 50 over the Tschebyscheffian range $-\kappa$ to $+\kappa$. The deviation $\log H$ is the same for all maxima and minima of any one curve.

The distance, $\log H$, decreases and the number of interior maxima and minima increases, as the 55 class number increases, for the same, given κ . For example, curve *f* has a greater number of maxima and minima than curve *e*, which, in turn, has a greater number than curve *d*, and so on. Again, the distance $\log H$, as may be seen by inspection of Fig. 19, is smaller for the curve *f* than for curve *e*, and is smaller for curve *e* than for curve *d*, and so on. It will thus be seen that the greater the class number and, therefore, the smaller the value of $\log H$, the better the approximation to the ideal, limiting requirement that $z_1 z_2 = 1$.

If, for a given class number, the limiting frequency κ is chosen nearer and nearer to the cut-off frequency $\Omega=1$, then $\log H$ approaches nearer and nearer to infinity. To maintain a given value of $\log H$, therefore, if κ is increased, it is necessary to choose a filter of higher class.

The best parameters for a band-pass filter, so as to improve the attenuation and impedance characteristics, may be chosen, according to my

invention, where the following two requirements are fulfilled. First, the best parameters for the image or surge impedance, for a given class, are obtained when

$$Z = \sqrt{z_1 z_2}$$

behaves in the manner just described in the frequency interval

$$\omega_1 < \omega < \omega_2$$

10 which corresponds to the normalized frequency interval

$$-\kappa < \Omega < \kappa$$

before mentioned. Secondly, the best parameters for the attenuation constant A_1 , for a given class, 15 are obtained by the use of another set of similar curves in two other normalized frequency intervals

$$\kappa_1 < \Omega < \kappa_2 < -1$$

and

$$1 < \kappa_3 < \Omega < \kappa_4$$

The values of ω corresponding to κ_1 and κ_4 may be such that above or below those values, there will be no attenuation requirement. The value of A_1 thus obtained may require certain corrections for resistance and for proximity to the limiting frequencies, when it is desired to obtain final values of the attenuation constant. The values of ω corresponding to κ_1 and κ_4 may be such that above 30 and below them no requirements regarding the attenuation have to be met. In particular, ω_{κ_1} may be zero and ω_{κ_4} may be infinite. The values κ_2 and κ_3 may be chosen as near as possible to the cut-off frequencies

$$\Omega = -1$$

and

$$\Omega = +1,$$

respectively, but they can never become quite 40 equal to these cut-off frequencies.

In Fig. 16 are shown attenuation curves 1, 2, 3, 4, 5, 6 representing

$$\sqrt{\frac{z_2}{z_1}}$$

45 for a band-pass filter, but on a particular ordinate scale. The ordinate is the attenuation constant A_1 , hereinabove defined. To the straight lines

$$50 \quad \log \sqrt{\frac{z_2}{z_1}} = \log H$$

of Fig. 15, as for example, the lines f_1 and f_2 , there corresponds in Fig. 16 a line of minimum 55 attenuation

$$A_1 \text{ min} = \text{constant} = 4.7 \text{ in the plot}$$

which relates to the minimum attenuation above (or below) a certain frequency $\kappa_3(\kappa_2)$. In Fig. 16, there are shown different curves 1, 2, 3, 4, 5, 6 for the same $\log H$, but these curves relate to different values of κ_3 . It will be observed that, in the higher classes, for the same minimum damping, attenuation requirement,

$$A_1 \text{ min} = 4.7$$

the value of κ_3 approaches more and more to the cut-off frequency $\Omega=1$. The value of κ_3 is shown 70 in Fig. 16 by a small circle on the axis of abscissæ at its value for class 6.

It will be understood that the full attenuation curves are not shown in Fig. 16, because the portions of the curves to the left of $\Omega=-1$ are reflec-

tions of the portions shown, and there is no attenuation in the interval

$$-1 < \Omega < 1$$

5 Corresponding considerations apply to other types of filters than the band-pass filter. For example, the curves of Fig. 15 may be the

10 $\sqrt{\frac{z_2}{z_1}}$ and $\sqrt{\frac{z_1}{z_2}}$ are straight lines, and the corresponding curves for a low-and-high pass filter. If Ω be changed to

$$\frac{1}{\Omega}$$

15 curves for

$$\sqrt{z_1 z_2}$$

will be obtained for a low-and-high-pass filter. In such cases, the straight line

$$\sqrt{z_1 z_2} = 1$$

20 cuts the curve e at $\Omega = \infty$.

When the arbitrary parameters are chosen in such a way that the attenuation and the image-impedance functions

$$\sqrt{z_1 z_2}$$

and

$$\sqrt{\frac{z_2}{z_1}}$$

30 or their corresponding curves, behave as just described, they will be said to exhibit a "Tschebycheff" behavior, and the said parameters will then be known as "Tschebyscheff" parameters. The various minima of attenuation over a prescribed part or parts of the attenuation region are substantially equal, and the various maxima and minima of surge impedance over a prescribed part or parts of the pass region all deviate to substantially the same extent from a predetermined value. The values of the Tschebyscheff parameters depend upon the frequencies of the first and the last maxima and minima (κ, κ^1). The intervals κ to κ^1 and so on will be referred to as "Tschebyscheff" intervals.

35 It is to be understood that the Tschebyscheff parameters are not unique, but that there may be different sets of such parameters, corresponding to different values of κ or $\log H$, for a given filter class. The choice of class and parameter is suggested by the practical requirements for the image-impedance

$$\sqrt{z_1 z_2}$$

40 and for the working attenuation A (it is to be noted that this A is not the same A as the A heretofore employed in the equation for E_1). This working attenuation is defined as

$$\log \left| \frac{J}{J_1} \right|$$

45 where J denotes the current flow in the receiving apparatus when it is directly or immediately connected with the sending apparatus, and where J_1 is the corresponding current when the wave filter is interposed between the sending and the receiving apparatus.

50 As I demonstrate in my above-mentioned paper on "Siebschaltungen", V. D. I. Verlag, Berlin, 1931, the working or total attenuation is constituted of two superposed parts, A_1 and A_2 , together with a correction term A_3 ,

$$55 A = A_1 + A_2 + A_3$$

A_1 , as has already been defined above, is a function of

$$\sqrt{\frac{z_2}{z_1}}$$

5

$$A_1 = \log \left| \frac{\sqrt{\frac{z_2}{z_1}} + 1}{\sqrt{\frac{z_2}{z_1}} - 1} \right|$$

10

$$A_2, similarly, is a function of$$

$$A_2 = \log \left| \frac{(\sqrt{z_1 z_2} + 1)^2}{4 \sqrt{z_1 z_2}} \right|$$

15

$$A_3 = \log \left| 1 - e^{-2[A_1 + A_2' + i(B_1 + B_2')]} \right|$$

20

where B_1 is the imaginary part of

$$\log \left| \frac{\sqrt{\frac{z_2}{z_1}} + 1}{\sqrt{\frac{z_2}{z_1}} - 1} \right|$$

25

$$A_1' + iB_1' = \log \left| \frac{\sqrt{z_1 z_2} + 1}{\sqrt{z_1 z_2} - 1} \right|$$

and

$$A_2' + iB_2' = \log \left| \frac{(\sqrt{z_1 z_2} + 1)^2}{4 \sqrt{z_1 z_2}} \right|$$

30

The ladder-type filter chain of Fig. 5 is constituted of simple, equal, four-terminal networks or sections, each section consisting of a series condenser 11 and a parallel-connected condenser 12 and inductance 13 in shunt. Each such section belongs to my class 1a. The filter chain of Fig. 6 is constituted of sections that differ more or less from one another. These sections are connected together and arranged according to the description by Otto J. Zobel, and is known as his M-type, with $m=0.6$. Compare his paper on "Theory and design of uniform and composite electric wave filters" in the Bell System Technical Journal, vol. II, No. 1, January, 1923, page 30. This filter belongs to my class 6d*. A number of variations of such special networks or classes of networks have been proposed and used in the prior art for the selection and propagation of prescribed ranges of frequency. It will now be understood that my invention is an improvement over these old circuits in several particulars, among them, that I am able to meet demands for which the prior-art circuits were not adapted, and even in those cases where they were more or less satisfactory, I am able to provide better parameters so as to render these old types of circuits more efficient.

35 In order the better to understand how the parameters of these filters may be improved in accordance with the present invention, let the number of sections of the filter of Fig. 5 be represented by the number v . Then the filter has an attenuation class v . The corresponding attenuation constants A_1 , for each of the six classes,

$$40 v = 1, 2, 3, 4, 5, \text{ and } 6$$

45 are represented by the curves

$$50 1, 2 \times 1, 3 \times 1, 4 \times 1, 5 \times 1, \text{ and } 6 \times 1$$

55 respectively, of Fig. 16, which show, in each case, the first branch only of the curve. Curve 6' of Fig. 16, similarly, is the attenuation curve of the filter shown in Fig. 6. It requires no more than a mere comparison of these curves to demonstrate the improvement obtained by the use of the Tschebyscheff parameters. For example, a filter

75

of my class 4, with the best parameters, will give the same results as, or better than, those obtained with the circuit of Fig. 6 and with poorer parameters. This is for the attenuation requirement

5

$$A_{1 \min} = 4.7$$

In the curves of Figs. 15 and 16, the ohmic resistances, for simplicity, have been neglected, but it is possible to correct the curves for such resistances, so that the method of the present invention is perfectly general.

According to present-day practice, the image impedances of known filters are designed with the aid of end circuits. A serious disadvantage of this practice, if a good image-impedance characteristic is desired, is that the attenuation is unnecessarily partly determined thereby, with consequent loss of efficiency. Thus, a necessary consequence of the design of Zobel's M-type ($m=0.6$) circuit, Fig. 6, is that frequency values of infinite attenuation are

$$\Omega = \pm 1.25$$

In designing filter circuits according to my invention, on the other hand, the attenuation and the image-impedance characteristics may be chosen quite independently of one another, and their values are not dependent upon the presence of any particular, single parts of the circuit, such as the end circuits.

All Tschebyscheff parameters may be computed by formulas mathematically derived in my paper, entitled "Ein Interpolationsproblem mit Funktionen mit positiven Realteil" in the Mathematische Zeitschrift, 1933, as follows:

35

(I)

$$40 \quad y_1 = \frac{1}{H} \sqrt{\frac{u}{u-1}} \cdot \frac{\prod_{r=1}^s \left(u - s n^2 \frac{2rK}{p} \right)}{\prod_{r=1}^s \left(u - s n^2 \frac{2r-1}{p} K \right)}$$

45

$$\frac{\sqrt{H^4 - 1}}{H^4} = k^p \left(\prod_{r=1}^s \frac{s n^2 \frac{2r-1}{p} K}{p} \right)^4$$

50

$$s = \frac{p-1}{2}$$

when p is odd

(II)

55

$$\frac{p-1}{2} \\ \prod_{r=1}^s \Omega - (-1)^r + \frac{p-1}{2} s n^2 \frac{2r-1}{p} K$$

60

$$y_2 = \sqrt{\frac{\Omega+1}{\Omega-1}} \frac{\prod_{r=1}^s \frac{p-1}{p-1}}{\prod_{r=1}^s \Omega + (-1)^r + \frac{p-1}{2} s n^2 \frac{2r-1}{p} K}$$

65

$$\frac{p-1}{2} \\ \frac{H^2 - 1}{H^2 + 1} = k^p \left(\prod_{r=1}^s \frac{2r-1}{p} K \right)^4$$

70

where
 sn stands for the Jacobian elliptic function,
 k , the modulus;

$$\frac{1}{K}$$

75 normalized limit of the Tschebyscheffian interval,

K , the complete elliptic integral of the first kind.

H , the maximum value of image impedance divided by R in an interval of Tschebyscheff behavior (this is the same H hereinbefore mentioned), and

$$\frac{qK}{p}$$

(p, q being whole numbers, $q < p$) the normalized resonance and antiresonance frequency parameters.

The minimum value of the attenuation constant in an interval of Tschebyscheff behavior is

$$A_{1 \min} = \log \frac{H+1}{H-1}$$

sn and K may be calculated in any well known manner, as with the aid of the formulas and tables in Funktionentafeln, by Jahnke and Emde.

The value $A_{1 \min}$ exists at certain special frequencies only, and the above Formulas (I) and (II) express the following law for those special frequencies: The various equal minima of the attenuation occur at those normalized frequencies that are equal to the ratio between the normalized limits of the Tschebyscheffian intervals and the normalized resonance and anti-resonance frequencies of the attenuation function. A similar law holds good for the position of the various minima and maxima of the image (surge) impedance.

Using the above Formulas (I) and (II), the values of z_1 and z_2 for the filter in question may be obtained by suitable transformations. Thus, for a low-pass filter in the Tschebyscheff interval

$$\omega_{k_1} < \omega < \omega_{k_2}$$

where

$$\omega_1 < \omega_{k_1} < \omega_{k_2}$$

the Tschebyscheff parameters for the classes

$$p = 1, 2, 3, \dots$$

45 may be obtained as follows from Equations (I) :

$$\sqrt{\frac{z_2}{z_1}} = y_1$$

when p is odd, and

$$\sqrt{\frac{z_2}{z_1}} = \frac{1}{y_1}$$

when p is even.

Similarly, for a high-pass filter in the same Tschebyscheff interval, the corresponding Tschebyscheff parameters for the same classes may be obtained from the following equations:

$$\sqrt{z_1 z_2} = y_1$$

when p is odd, and

$$\sqrt{z_1 z_2} = \frac{1}{y_1}$$

when p is even.

In both cases

$$u = \frac{(\omega_{k_2}^2 - \omega^2) \omega^2}{(\omega_{k_2}^2 - \omega^2) \omega_1^2}$$

and

$$k = \sqrt{\frac{\omega_{k_2}^2}{\omega_{k_1}^2} - 1}$$

5

15

30

35

40

50

55

60

65

70

75

which reduce, in the special case where

$$\omega_{k2} = \omega_{k1} = \omega_k$$

and

$$\omega_{k1} = \omega_k$$

to the simpler formulas:

$$u = \frac{\omega_1^2}{\omega_k^2}$$

$$k = \frac{\omega_1}{\omega_k}$$

10

It is necessary to obtain also the Tschebyscheff parameters for the filter classes

15

corresponding to

$$p = 1, 2, 3, \dots$$

For the low-pass filter in the Tschebyscheff interval

20

$$\omega_{k2} < \omega < \omega_{k1}$$

where

$$\omega_{k2} < \omega_{k1} < \omega_1$$

25

these may be obtained by the equations

$$\sqrt{z_1 z_2} = y_1$$

when p is odd, and

$$\sqrt{z_1 z_2} = \frac{1}{y_1}$$

30

when p is even.

For the corresponding high-pass filter in the same Tschebyscheff interval, the equations to be used are

$$\sqrt{z_2 z_1} = y_1$$

when p is odd, and

$$\sqrt{z_2 z_1} = \frac{1}{y_1}$$

40

when p is even.

Here,

$$u = \frac{\omega_1^2 - \omega_{k2}^2}{\omega_1^2 - \omega_{k1}^2}$$

45

and

$$k = \sqrt{\frac{\omega_{k1}^2 - \omega_{k2}^2}{\omega_{k1}^2 - \omega_{k2}^2}},$$

and in the special case where

50

$$\omega_{k2} = 0$$

and

$$\omega_{k1} = \omega_k$$

these become

55

$$u = \frac{\omega_1^2}{\omega^2}$$

$$k = \frac{\omega_k}{\omega}$$

60

the reciprocals of the corresponding values obtained in the above-discussed special case for the low-pass (or high-pass) classes 1, 2, 3, . . .

65

Formulas somewhat similar to these may be obtained, by suitable transformations from the same Formulas (I), for band-pass filter and for low-and-high-pass filter classes

$$n = 2p = 2, 4, 6, \dots$$

and let

70

$$\omega_{-k2} < \omega_{-k1} < \omega_{-1} < \omega_1 < \omega_{k1} < \omega_{k2}$$

Then, in the Tschebyscheff interval

$$\omega_{-k2} < \omega < \omega_{-k1}$$

and

$$\omega_{k1} < \omega < \omega_{k2}$$

for a band-pass filter.

$$\left(\frac{z_2}{z_1} = y_1 \right)$$

when p is odd,

$$\left(\frac{z_2}{z_1} = \frac{1}{y_1} \right)$$

when p is even; and for a low-and-high-pass filter, in the same Tschebyscheff intervals,

$$\sqrt{z_1 z_2} = y_1$$

when p is odd, and

$$\sqrt{z_1 z_2} = \frac{1}{y_1}$$

when p is even. In both cases,

$$\mu = \frac{(\tau - 1) \Omega^2}{\tau^2 - \Omega^2}$$

and

$$\Omega = \frac{(\sigma + 1) \omega_1^2 + \sigma \omega_{-1}^2 - \omega_1^2}{(\sigma - 1) \omega_1^2 - \sigma \omega_{-1}^2 + \omega_1^2}$$

where

$$\sigma = \sqrt{\frac{(\omega_{k1}^2 - \omega_1^2)(\omega_1^2 - \omega_{-k1}^2)}{(\omega_{k1}^2 - \omega_1^2)(\omega_1^2 - \omega_{-k1}^2)}}$$

$$\tau = \frac{(\sigma + 1) \omega_{k2}^2 - \sigma \omega_{-k2}^2 - \omega_1^2}{(\sigma - 1) \omega_{k2}^2 - \sigma \omega_{-k2}^2 + \omega_1^2}$$

and

$$k = \sqrt{\frac{(1 - \rho)^2 - 1}{(1 + \rho)^2 - 1}}$$

where

$$\rho = \sqrt{\frac{(\omega_{k1}^2 - \omega_1^2)(\omega_1^2 - \omega_{-k1}^2)}{(\omega_{k1}^2 - \omega_1^2)(\omega_1^2 - \omega_{-k1}^2)}}$$

In these formulas,

$$\omega_{-k1}, \omega_{-1}$$

and

$$\omega_{k1}$$

may be chosen arbitrarily, whereupon

$$\omega_{-k2}$$

will be determined by the formula

$$\omega_{k2}^2 = \frac{\omega_1^4 - \sigma^2 \omega_{-1}^4 + (\sigma \omega_{-1}^2 - \omega_1^2) \omega_{-k2}^2}{\omega_1^2 - \sigma^2 \omega_{-1}^2 + (\sigma^2 - 1) \omega_{-k2}^2}$$

In case of symmetry,

$$\sigma = 1$$

and a simple algebraic reduction will then show that

$$\omega_{-k2}^2 + \omega_{k2}^2 = \omega_{-1}^2 + \omega_1^2$$

The above formulas then reduce to the following much simpler form:

$$u = \left[\left(\frac{\omega_{k2}^2 - \omega_{-k2}^2}{\omega_{k1}^2 - \omega_{-k1}^2} \right)^2 - 1 \right]$$

$$\frac{(2\omega_1^2 - \omega_{-1}^2 - \omega_1^2)^2}{(\omega_{k2}^2 - \omega_{-k2}^2)^2 - (2\omega_1^2 - \omega_{-1}^2 - \omega_1^2)^2}$$

$$k = \sqrt{\frac{(\omega_{k2}^2 - \omega_{-k2}^2)^2 - 1}{(\omega_{k1}^2 - \omega_{-k1}^2)^2 - 1}}$$

also,

$$\omega_{-k2}^2 + \omega_{k2}^2 = \omega_{-1}^2 + \omega_1^2$$

In the limiting case, where

$$\omega_{-k1}^2 = \omega_{-1}^2$$

approaches infinity, and still retaining

$$\sigma = 1$$

70

75

these reduce to the still simpler form:

$$u = \frac{(2\omega^2 - \omega_1^2 - \omega_{-1}^2)^2}{\omega_1^2 - \omega_{-1}^2}$$

$$k = \frac{\omega_1^2 - \omega_{-1}^2}{\omega_{-1}^2 - \omega_1^2}$$

Again, if it be assumed that

$$\sigma = \frac{\omega_1}{\omega_{-1}}$$

and

$$r = \frac{\omega_1 + \omega_{-1}}{\omega_1 - \omega_{-1}}$$

the following, simple, frequency transformation is obtained:

$$u = \frac{(\omega^2 - \omega_{-1}\omega_1)^2}{(\omega_1 - \omega_{-1})^2\omega^2}$$

To obtain the Tschebyscheff parameters for the band-pass filters and the low-and-high-pass filters for the classes

$$p = 1, 3, 5, \dots$$

in the Tschebyscheff intervals for ω^2

and

$$\omega_{-k}^2 < \omega^2 < \omega_k^2$$

where

$$\omega_{-k} < \omega_{-1} < \omega_1 < \omega_k$$

resort is had to Formulas (II). For a band-pass filter

$$\sqrt{\frac{z_2}{z_1}} = y_2$$

and for a low-and-high-pass filter,

$$\sqrt{z_1 z_2} = y_2$$

In both cases,

$$\Omega = \frac{(\sigma + 1)\omega^2 - \sigma\omega_{-1}^2 - \omega_1^2}{(\sigma - 1)\omega^2 - \sigma\omega_{-1}^2 + \omega_1^2}$$

$$k = \frac{1 - \rho}{1 + \rho}$$

where

$$\sigma = \sqrt{\frac{(\omega_k^2 - \omega_1^2)(\omega_1^2 - \omega_{-1}^2)}{(\omega_k^2 - \omega_{-1}^2)(\omega_1^2 - \omega_{-k}^2)}}$$

and

$$\rho = \sqrt{\frac{(\omega_k^2 - \omega_1^2)(\omega_{-1}^2 - \omega_{-k}^2)}{(\omega_k^2 - \omega_{-1}^2)(\omega_1^2 - \omega_{-k}^2)}}$$

In class 3, for example,

$$m = \sqrt{\sigma} \cdot \frac{1 + \sigma + (1 - \sigma) \operatorname{sn} \frac{K}{3}}{1 + \sigma - (1 - \sigma) \operatorname{sn} \frac{K}{3}}$$

$$\omega_{\pm k}^2 = \frac{\sigma\omega_{-1}^2(1 \mp \operatorname{sn} \frac{K}{3}) + \omega_1^2(1 \pm \operatorname{sn} \frac{K}{3})}{\sigma + 1 \mp (\sigma - 1) \operatorname{sn} \frac{K}{3}}$$

In case of symmetry,

$$\sigma = 1$$

whence

$$\omega_{-k}^2 + \omega_k^2 = \omega_{-1}^2 + \omega_1^2$$

so that

$$\Omega = \frac{2\omega^2 - \omega_{-1}^2 - \omega_1^2}{\omega_1^2 - \omega_{-1}^2}$$

$$k = \frac{\omega_1^2 - \omega_{-1}^2}{\omega_k^2 - \omega_{-k}^2}$$

To obtain the Tschebyscheff parameters for the band-pass filter classes

$$b, d, f, \dots$$

corresponding to

$$p = 1, 2, 3, \dots$$

in the Tschebyscheff interval

$$\omega_{-k} < \omega < \omega_k$$

where

$$\omega_{-k} < \omega_{-1} < \omega_1 < \omega_k$$

and

$$\omega_{-k} = \omega_{-1}\omega_1$$

the following formulas, obtained from Formulas 15 (I) are appropriate:

$$\sqrt{z_1 z_2} = y_1$$

when p is odd, and

$$\sqrt{\frac{z_2}{z_1}} = \frac{1}{y_1}$$

when p is even.

The corresponding formulas for low-and-high-pass filter classes $b, d, f, \dots$ are

$$\sqrt{\frac{z_2}{z_1}} = y_1$$

when p is odd, and

$$\sqrt{\frac{z_2}{z_1}} = \frac{1}{y_1}$$

when p is even.

In both cases,

$$\mu = \frac{(\omega_1 - \omega_{-1})^2 \omega^2}{(\omega^2 - \omega_{-1}\omega_1)^2}$$

and

$$k = \frac{\omega_k - \omega_{-k}}{\omega_1 - \omega_{-1}}$$

As an illustration, for class b ,

$$\sqrt{z_1 z_2} = \frac{\omega_1 - \omega_{-1}}{H} \cdot \frac{\lambda}{\sqrt{(\lambda^2 + \omega_{-1}^2)(\lambda^2 + \omega_1^2)}}$$

and for class d ,

$$\sqrt{z_1 z_2} = \frac{H \operatorname{sn}^2 \frac{K}{2} (\lambda^2 + \omega_{-1}^2)(\lambda^2 + \omega_1^2)}{(\omega_1 - \omega_{-1}) \lambda \sqrt{(\lambda^2 + \omega_{-1}^2)(\lambda^2 + \omega_1^2)}}$$

where

$$\omega_{\pm k}^2 = \omega_{-1}\omega_1 \pm \frac{(\omega_1 - \omega_{-1})^2}{2 \operatorname{sn}^2 \frac{K}{2}} \cdot \left[\sqrt{1 + \frac{4\omega_1 \omega_{-1} \operatorname{sn}^2 \frac{K}{2}}{(\omega_1 - \omega_{-1})^2}} \pm 1 \right]$$

and

$$\frac{1}{\operatorname{sn}^2 \frac{K}{2}} = 1 + \sqrt{1 - k^2}$$

Finally, the Tschebyscheff parameters for band-pass filters (and correspondingly for low-and-high-pass filters, as will now be understood) of classes

$$a, c, e, \dots$$

corresponding to

$$p = 1, 3, 5, \dots$$

may be approximately obtained, for narrow bands, that means for

$$\frac{\omega_1 - \omega_{-1}}{\omega_1 + \omega_{-1}} \ll 1$$

from Formulas (II) by the substitution

$$\Omega = \frac{\omega_1 - \omega_{-1}}{2\omega_1 - \omega_{-1} - \omega_1}$$

If the Tschebyscheff interval is

$$\omega_K < \omega < \omega_K$$

where

$$\omega_{-1} < \omega_K < \omega_K < \omega_1$$

5 and

$$\omega_K + \omega_K = \omega_{-1} + \omega_1$$

then

$$10 \quad k = \frac{\omega_K - \omega_K}{\omega_1 - \omega_{-1}}$$

Letting

$$15 \quad \omega_0 = \frac{\omega_1 + \omega_{-1}}{2}$$

the following equations may be derived:

For class *a*,

$$\sqrt{z_1 z_2} = \frac{\omega_0 \sqrt{\lambda^2 + \omega_{-1}^2}}{\lambda \sqrt{\lambda^2 + \omega_1^2}} \cdot \left[\frac{\omega}{\omega_0} \sqrt{\frac{\omega + \omega_1}{\omega + \omega_{-1}}} \right]$$

20 For class *c*,

$$\sqrt{z_1 z_2} = \frac{\lambda \sqrt{\lambda^2 + \omega_{-1}^2} (\lambda^2 + \omega_{-1}^2)}{\omega_0 (\lambda^2 + \omega_{-1}^2) \sqrt{\lambda^2 + \omega_1^2}} \cdot \left[\frac{\omega_0}{\omega} \sqrt{\frac{\omega + \omega_1}{\omega + \omega_{-1}}} \cdot \frac{\omega + \omega_{-1}}{\omega + \omega_{\alpha}} \right]$$

where

$$25 \quad \omega_{\alpha} = \omega_0 \pm \frac{\omega_1 - \omega_{-1}}{2 \sin \frac{K}{3}}$$

For class *e*,

$$30 \quad \sqrt{z_1 z_2}$$

is the value given for class *e* in Table II, multiplied by

$$35 \quad \left[\frac{\omega}{\omega_0} \sqrt{\frac{\omega + \omega_1}{\omega + \omega_{-1}} \frac{(\omega + \omega_{-1})(\omega + \omega_{\beta})}{(\omega + \omega_{\alpha})(\omega + \omega_{\beta})}} \right]$$

For class *g*,

$$\sqrt{z_1 z_2}$$

40 is the value given for class *g* in Table II, multiplied by

$$45 \quad \left[\frac{\omega_0}{\omega} \sqrt{\frac{\omega + \omega_1}{\omega + \omega_{-1}} \frac{(\omega + \omega_{-1})(\omega + \omega_{\beta})(\omega + \omega_{\gamma})}{(\omega + \omega_{\alpha})(\omega + \omega_{\beta})(\omega + \omega_{\gamma})}} \right]$$

and so on.

45 For narrow bands, the quantities in the brackets of these formulas may, for practical purposes, and without substantial loss of accuracy, be considered as constants in certain neighborhoods of the bands.

50 As is demonstrated by the mathematical theory developed in my said paper in the Matematische Zeitschrift, it is possible to use also other very favorable parameters, though not necessarily Tschebyscheff parameters, particularly in the design of more complicated filters, and more especially filters with more than two bands. These are not enumerated in detail herein, merely in order to save space, and it is therefore desired that the mathematical treatment given in the said paper be considered as embodied herein and considered a part hereof. Such complicated filters may be distinguished by the number of points in which the characteristic curve corresponding to

$$65 \quad \sqrt{z_1 z_2}$$

(or, as the case may be, to

$$70 \quad \sqrt{\frac{z_2}{z_1}})$$

75 is intersected in the most favorable case by a parallel to the abscissa axis of frequency in the transmission (or, as before stated, the attenuation) bands. For example, in Fig. 15, the curve

80 *d* will be intersected by such a horizontal line, in the transmission band, at four points, two of which will be visible in Fig. 15, and the other two are the reflections thereof. The multi-band filters, in accordance with the present invention, are such that it is possible so to choose the said horizontal line that it shall intersect the characteristic curve in at least four points in each transmission band.

85 The desirability has been recognized of having the image impedance of a filter as nearly constant as possible in the transmission bands, but this has never heretofore been possible of attainment except to a very rough degree of approximation. According to my invention it is 15 possible to attain this result to any desired degree of accuracy.

90 One advantage of the use of Tschebyscheff parameters is the possibility of reducing the classification number of a filter circuit that has to 20 satisfy given attenuation and surge-impedance requirements.

95 Using these methods, it is possible to choose the number, size and classes of the elements, both capacitative and inductive, so as to yield the most 25 desirable results, with a smaller number of circuit elements, as described more fully hereinafter. Usually, the emphasis is placed upon the number and size of the inductances, as they are the more expensive elements, but it will be understood that 30 economy is equally possible in connection with the capacities.

100 It has now been shown how to obtain the functions z_1 and z_2 to be used, for example, in the required filter circuit of Fig. 1, and how to obtain, 35 also, the best parameters for such functions. It should now be explained, however, that corresponding to each set of functions z_1 and z_2 thus obtained, there are many different, though electrically equivalent, filter circuits. This will be 40 understood by persons skilled in the art without further description, though reference may be made to a paper by R. M. Foster in the Bell System Technical Journal, vol. 3, April 1, 1924, as well as to my paper in the Archiv für Elektrotechnik for 1926. In my said paper in the Matematische Annalen, as well as in my said paper in the Elektrische Nachrichtentechnik, vol. VI, 1929, at page 272, indeed, it is explained how to construct all circuits corresponding and equivalent to 45 any given network. If the frequency characteristics of a filter be expressed in algebraic form, the corresponding filter can be constructed in known manner from the partial or continued fractions in which this form may be expressed. The 50 suitable algebraic form thus serves completely to define a filter, together with its equivalent filters. It will now be clear that these equivalent circuits are related to each other not, in general, by the arrangement and connection of the elements or 55 sections of which they are composed as, for example, in the form of a chain like in Figs. 5 and 6, but rather by the nature of the rational functions z_1 and z_2 . To each choice of these functions there corresponds a large number of equivalent circuits, several examples of which are illustrated in the drawings.

60 One such circuit, as will now be understood, is illustrated in Fig. 1, assuming that z_1 and z_2 are 65 of the form illustrated in Fig. 2.

65 The impedance z_1 of Fig. 2, may be constituted of an inductance 3, in series with a capacity 4, and with a number of parallel-connected inductances 5 and capacities 6. The inductances 70

- 3 and 5 are indicated as having the values L_1 and $L_2, L_3, \dots, L_r$, respectively, and the condensers 4 and 6 the reciprocal values $D_1, D_2, D_3 \dots, D_r$, respectively. The impedance z_1 of Fig. 5 2 similarly constituted of a condenser 7, having a reciprocal value D_{r+1} , in series with an inductance 8, having a value L_{r+1} and with groups of similarly parallel-arranged groups of inductances and capacities 9, 10, having inductance values $L_{r+2}, 10 L_{r+3} \dots, L_m$, and reciprocal capacity values $D_{r+2}, D_{r+3} \dots, D_n$, respectively.

- The filter network of Fig. 4, like that of Fig. 1, has two input terminals 1, 1 and two output terminals 2, 2. The indicated values of inductance 15 and reciprocal capacities are the same as in Fig. 2. Between the left-hand terminals 1, 2, as viewed in Fig. 4, there are connected, in series, two capacities 11 having reciprocal values D_{r+1} . At a point between these two condensers, there is connected 20 a further capacity 12 having a reciprocal value $\frac{1}{2}(D_1 - D_{r+1})$. In the event that $D_{r+1} > D_1$, then the same construction will be used, except that z_1 and z_2 will be interchanged in Fig. 2. A coil 13 with inductance

25
$$\frac{L_1}{2}$$

- is connected in series with the capacity 12. Further connected in series are a number of parallel-connected groups of inductances 14 and capacities 30 15 having values

$$\frac{L_2, D_2}{2}, \dots, \frac{L_r, D_r}{2}, \frac{L_{r+2}, D_{r+2}}{2}, \dots, \frac{L_n, D_n}{2}$$

- 35 These are connected in series to the other terminal 1 through a series connected inductance 16 having a value

$$\frac{L_{r+1}}{2}$$

- 40 The coils marked

$$\frac{L_{r+2}}{2}, \dots, \frac{L_n}{2}, \frac{L_{r+1}}{2}$$

- 45 are individually tightly coupled to other coils 17, 18, 19, as illustrated, so as to produce a one-to-one ratio in the resulting transformers, these coils 17, 18, 19 being connected in series to a point between the coils marked

50
$$\frac{L_r}{2} \text{ and } \frac{L_{r+2}}{2}$$

- and to the other terminal 2. The ratio is marked on the drawings $-1:1$. This is to explain that the points 20 and 21, for example have not the same voltage. If they had had the same voltage, the ratio could have been $1:1$ and the coil 17 might have been omitted.

- The network of Fig. 4 comprises two circuits: 60 one, from the first input terminal 1, through the upper condenser 11, the condenser 12, the coil 13, all the coils 14, and the coil 16, to the second input terminal 1; the other, from the third or output terminal 2, through the lower condenser 11, the condenser 12, the coils 14 and the coils 65 17, 18 and 19, to the fourth or output terminal 2.

- These two circuits are inductively coupled positively to the left of the said point between the coils marked

70
$$\frac{L_r}{2} \text{ and } \frac{L_{r+2}}{2}$$

- and inductively coupled negatively to the right of the said point. The negative coupling is indicated by the ratios $-1:1$. To the left of the 75 said point, the circuits have a coil or coils in

common, but to the right of the said point, the circuits are separate.

It will be understood that the invention comprises all cases of filter networks derived according to my formulas and having one circuit through the input terminals and another circuit through the output terminals, the circuits being inductively coupled to one side and to the other side of an intermediate point, and an inductive coupling to one side of the intermediate point being negative relative to an inductive coupling to the other side of the intermediate point. The coupling may, in particular, be realized by common coils, or by tight couplings or by a combination of the same.

It may be shown that the circuit diagram of Fig. 4 represents a circuit equivalent to the circuit obtained by replacing z_1 and z_2 from Fig. 2 in Fig. 1. This may be demonstrated mathematically, using a linear, affine transformation, as described in my said paper in the Jahressbericht der deutsches Mathematikervereinigung and in the said paper in the Mathematische Annalen. It will be made obvious also, by calculating the open-circuit and the short-circuit impedances in both figures. For example, if the terminals 2, 2 be regarded as open-circuited both in Figs. 1 and 4, then the impedance across the terminals 1, 1 in Fig. 1 is

$$\frac{z_1 + z_2}{2}$$

as is obvious on mere inspection; and the same is true of Fig. 4.

It has now been shown how to obtain any desired filter network, old or new, and how to evaluate the best parameters therefor. A further feature of the invention was stated above to reside in the reduction of the number of circuit elements that need be employed in such circuits, thus reducing their cost of manufacture.

The filter circuit represented in Fig. 4, which may be termed the "canonical" circuit of which all circuits of the corresponding class are equivalents, has, in general, the minimum number of capacitative and inductive elements.

Mention has been made above of the fact that the invention is not restricted to the design of symmetrical filter circuits, and one unsymmetrical circuit in accordance with my invention is illustrated diagrammatically in Fig. 3. In my said paper in the Mathematische Annalen, 1931, I have demonstrated that this is a canonical form of circuit which, by suitable dimensions and choices of its elements, may be made equivalent to any unsymmetrical four-terminal network with negligible resistances. This canonical form of circuit comprises a number of parallel-connected coils and condensers 24, 25 arranged in series with a coil 26 and a condenser 27, the last-named condenser 27 having a shunt-arranged coil 28 and condenser 29. An ideal transformer T is connected in this shunt circuit. By "ideal" is meant a tightly-coupled transformer having great inductance. The arrows connect coils that are mutually inductively related, and only the coils so indicated by the arrows are so related.

This canonical circuit is equivalent to a symmetrical wave-filter circuit connected in series with a transformer T, or a phase-corrective network, or both. If the network is symmetrical, the circuit of Fig. 3 may be shown easily to be convertible into, and equivalent to, the circuit of Fig. 4.

In order to save circumlocution of language in

the claims, the expression "network with frequency characteristics z_1 and z_2 ," or its equivalent, will be used to include not merely a symmetrical network but, more generally, a symmetrical network in series with a transformer, or which is equivalent to such a series connection. An example of such equivalence will be found in Fig. 19 of my said paper, entitled *Siebschaltungen*, in V. D. I.—Verlag, Berlin, 1931.

Further examples of circuits are given in Figs. 7 to 14.

The filter of Fig. 7 is a special case of Fig. 1 with values of z_1 and z_2 such as to place the filter in class 3b. The coils having the same letters are on a single core, with the result that, for manufacturing purposes, they may be considered as a single coil, thus reducing the number of coils required by the filter. It is always possible, in filter circuits of the type illustrated in Fig. 1, to place two opposite, symmetrically disposed coils on one core in this manner. Such circuits are desirable in cases of line balance where, for example, the unbalanced equivalent circuit of Fig. 8 could not be directly used, except with further inductive coupling and a change of connections. Fig. 8, of course, is a special case, of the more general case illustrated in Fig. 4, class 3b.

Fig. 10 illustrates a lattice network having four branches. The branches 1, 2 and the branches 1', 2' are equal to each other, as also are the branches 1, 2' and 1', 2. The branches 1, 2 and 1', 2' each contains a condenser 53, an inductance a and an inductance b in parallel with a condenser 54. The branches 1, 2' and 1', 2 similarly each have a condenser 55, an inductance c and an inductance d in parallel with a condenser 56. The coils a , a are mounted in a single core. The same is true of the coils b , b , as well as of the coils c , c and the coils d , d . This lattice-type network is useful as a wave-filter circuit of the class 3b* if the elements a , b , c , d , 53, 54, 55 and 56 are suitably chosen. Fig. 11 is an equivalent circuit to that of Fig. 10 and is a special case of Fig. 4.

Fig. 12 illustrates a multiple-inductance wave filter embodying the present invention, which can be made equivalent to the filter of Fig. 10 by suitable choice of dimensions of the elements and which contains a smaller number of capacities and also a more suitable choice of dimensions of the capacities than is true of the circuit of Fig. 10. This circuit comprises four branches, as in Fig. 10. The first branch contains a condenser 57, and two coils 58, 59 in series between the terminals 1, 2. The second branch, between the terminals 1, 2', contains a condenser 60 and two coils 61 and 62 in series. The third branch contains a condenser 63 and two coils 64, 65 between the terminals 1', 2'. The fourth branch contains a condenser 66 and two coils 67 and 68 between the terminals 1', 2.

The coils 58 and 64 are tightly coupled and mounted upon a single core 69. The same is true of the coils 61 and 67, upon a single core 70. The coils 59 and 65 are similarly mounted upon a single core 71 with a third coil 72, which latter is shunted by a condenser 73. It will be noted that the coils 59, 65 and 72 are none of them directly galvanically connected, but are mutually tightly coupled. A similar construction obtains for the coils 62 and 68 and a third coil 74, which latter is shunted by a condenser 75. The coils 62, 68 and 74 are tightly coupled and are all mounted upon a single core 76 similarly to the coils 59, 65 and 72.

In some cases, according to the present invention, two of the three mutually inductively related coils may be galvanically connected together. In all cases furthermore, the principle of the invention is unaffected if a direct galvanic connection is unaccompanied by a change of current, as such would not be an essential galvanic connection. It is to be understood, therefore, that the expression "direct galvanic connection", or its equivalent, as used in the specification and claims herein, has reference to an essential connection, and not to a connection that is not essential.

The six condensers 57, 60, 63, 66, 73 and 75 are smaller in number than the eight condensers 53, 54, 55, and 56 of Fig. 10. A further advantage of the circuit of Fig. 12 is to avoid too great capacities such as would be necessary, in practice, with the circuit of Fig. 10. The dimensions of the elements indicated in Fig. 12 were calculated beforehand for a given attenuation requirement and were actually checked experimentally.

Fig. 13 is a diagram illustrating a known, chain-type filter, with three equal sections, the whole filter being of class 3b*, each section, as shown in Fig. 14, being of class 1b*. Each branch contains a series combination of capacity 30 and inductance 31. It is always possible to make the circuits of Figs. 10, 11 and 12 equivalent to the wave filter of Fig. 13 by suitable size of the elements, but the converse is not true. The circuits of Figs. 10, 11 and 12 can be designed with better frequency characteristics than is the case with Fig. 13, using the Tschebyscheff parameters.

In the circuit of Fig. 13, there are six coils and twelve condensers, counting oppositely-disposed coils as single coils, as before described. The circuits of Figs. 10, 11 and 12 each have four coils, and eight condensers, five condensers and six condensers, respectively.

The circuit of Fig. 9 belongs to class 3b and is equivalent to the circuits of Figs. 7 and 8. The circuit elements of Fig. 9, therefore, are represented by the same symbols as in Fig. 7. The coils 35, 36 and 37 are tightly connected together. The coil 35 is connected across the terminals 1, 1' in series with a coil 38 and a condenser 39. The coil 36 is similarly connected between the terminals 1' and 2 by a conductor 40. The coil 37 is connected across the terminals 1 and 1' in series with a coil 41. A coil 42 and a condenser 43 are connected in series between the terminals 1 and 2 by the same conductor 40. A condenser 44 is connected between the terminals 1, 1'. A condenser 45 is connected between the terminals 2, 2'. A condenser 46 is connected anywhere between the terminals 1 and 2.

An inspection of the circuit of Fig. 9 will show that it contains a fewer number of elements than in the circuit of Fig. 7. Counting the coils 35, 36 and 37 as one element, as before described, the circuit of Fig. 9 contains four coils and five condensers. The circuit of Fig. 7, on the other hand, has four coils and eight condensers.

The equivalence of these two circuits may be demonstrated, for example, by calculating the short-circuit and the open-circuit impedances in both cases. The circuit of Fig. 9 was actually obtained by building the reciprocal of a filter of class 3b* designed in accordance with Fig. 3, without the transformer T. The method of obtaining such reciprocal is described more at length in my copending application on artificial networks, Serial No. 499,233, filed December 1, 1930 which has become U. S. Patent #1,958,742 May 15, 1934.

The known filter of Fig. 13 contains six coils and twelve condensers. It belongs to my class 3b*. One equivalent circuit, therefore, contains 4 coils and 5 condensers, as demonstrated in Fig. 11.

It is obviously impossible to describe in detail all the special applications of my invention. They will be understood by persons skilled in the art without further description. It is therefore desired that the appended claims be broadly construed, unlimited except insofar as limitations may be necessary to be imposed by the state of the prior art.

What I claim is:

1. A four-terminal, low-and-high-pass, filter network having frequency characteristics z_1 and z_2 , where

$$|\log \sqrt{z_1 z_2}|$$

equals

$$20 \quad \log m \frac{\sqrt{\lambda^2 + \omega_{-1}^2} (\lambda^2 + \omega_1^2)}{(\lambda^2 + \omega_{-n}^2) \sqrt{\lambda^2 + \omega_1^2}}$$

where m is an arbitrary, positive constant; λ is the imaginary, frequency parameter; ω_{-1} and ω_1 are cut-off frequencies; and ω_{-n} and ω_n are arbitrary resonant and anti-resonant frequency parameters in the attenuation band.

$$30 \quad \log \mu \frac{\lambda (\lambda^2 + \omega_{-n-2}^2) \dots (\lambda^2 + \omega_{-1}^2) (\lambda^2 + \omega_{-n-1}^2) \dots (\lambda^2 + \omega_{-n-2}^2) \sqrt{(\lambda^2 + \omega_{-1}^2) (\lambda^2 + \omega_1^2) (\lambda^2 + \omega_{-n}^2) \dots (\lambda^2 + \omega_{-1}^2)}}{(\lambda^2 + \omega_{-n}^2) \dots (\lambda^2 + \omega_{-1}^2) (\lambda^2 + \omega_{-n-1}^2) \dots (\lambda^2 + \omega_{-n-2}^2) \sqrt{(\lambda^2 + \omega_{-1}^2) (\lambda^2 + \omega_1^2) (\lambda^2 + \omega_{-n}^2) \dots (\lambda^2 + \omega_{-1}^2)}}$$

2. A four-terminal, low-and-high-pass, filter network of image-impedance class $2n-1$ or $2n-1^*$ having frequency characteristics z_1 and z_2 , where

$$|\log \sqrt{z_1 z_2}|$$

equals

$$40 \quad \log m \frac{\sqrt{\lambda^2 + \omega_{-1}^2} (\lambda^2 + \omega_{-n}^2) (\lambda^2 + \omega_{-n-1}^2) \dots (\lambda^2 + \omega_{-n-2}^2) \dots (\lambda^2 + \omega_{-1}^2) (\lambda^2 + \omega_{-n}^2) \dots (\lambda^2 + \omega_{-n-1}^2) \dots (\lambda^2 + \omega_{-n-2}^2) \sqrt{\lambda^2 + \omega_1^2}}{(\lambda^2 + \omega_{-n}^2) (\lambda^2 + \omega_{-n-1}^2) \dots (\lambda^2 + \omega_{-n-2}^2) \dots (\lambda^2 + \omega_{-1}^2) (\lambda^2 + \omega_{-n}^2) \dots (\lambda^2 + \omega_{-n-1}^2) \dots (\lambda^2 + \omega_{-n-2}^2) \sqrt{\lambda^2 + \omega_1^2}}$$

where n is any whole, positive number greater than 2; m is an arbitrary, positive constant; λ is the imaginary, frequency parameter; ω_{-1} and ω_1 are cut-off frequencies; and ω_{-n} etc. are arbitrary resonant and anti-resonant frequency parameters in the attenuation band.

3. A four-terminal, low-and-high-pass, filter network of image-impedance class $2n$ or $2n^*$ having frequency characteristics z_1 and z_2 , where

$$|\log \sqrt{z_1 z_2}|$$

equals

$$55 \quad \log m \frac{(\lambda^2 + \omega_{-1}^2) (\lambda^2 + \omega_{-n}^2) \dots (\lambda^2 + \omega_{-n-1}^2)}{\sqrt{\lambda^2 + \omega_{-1}^2} (\lambda^2 + \omega_{-n}^2) \dots (\lambda^2 + \omega_{-n-1}^2) \sqrt{\lambda^2 + \omega_1^2}}$$

where n is any whole, positive number greater than 2; m is an arbitrary, positive constant; λ is the imaginary, frequency parameter; ω_{-1} and ω_1 are cut-off frequencies; and ω_{-n} etc. are arbitrary resonant and anti-resonant frequency parameters in the attenuation band.

4. A four-terminal band-pass, filter network having frequency characteristics z_1 and z_2 , where

$$65 \quad |\log \sqrt{z_1 z_2}|$$

equals

$$70 \quad \log \mu \frac{\lambda \sqrt{\lambda^2 + \omega_{-1}^2} (\lambda^2 + \omega_1^2)}{(\lambda^2 + \omega_{-n}^2) \sqrt{\lambda^2 + \omega_1^2}}$$

where μ is an arbitrary, positive constant; λ is the imaginary, frequency parameter; ω_{-1} and ω_1 are cut-off frequencies; and ω_{-n} and ω_n are arbitrary resonant and anti-resonant frequency parameters in the attenuation bands.

5. A four-terminal, band-pass, filter network of image-impedance class a_{2n-1} or a_{2n-1}^* having frequency characteristics z_1 and z_2 , where

$$5 \quad |\log \sqrt{z_1 z_2}|$$

equals

$$|\log \mu \frac{(\lambda^2 + \omega_{-1}^2) \dots (\lambda^2 + \omega_{-n}^2) \sqrt{\lambda^2 + \omega_1^2}}{(\lambda^2 + \omega_{-n}^2) \dots (\lambda^2 + \omega_{-1}^2) \sqrt{\lambda^2 + \omega_1^2}}|$$

image-impedance class α_{2n-1} or α_{2n-1}^* having frequency characteristics z_1 and z_2 , where

5 equals

$$\log \mu \frac{(\lambda^2 + \omega_{\alpha,1}^2) \cdots (\lambda^2 + \omega_{\alpha,2n-3}^2)}{\sqrt{\lambda^2 + \omega_1^2}(\lambda^2 + \omega_{\alpha,2}^2) \cdots (\lambda^2 + \omega_{\alpha,2n-2}^2)}$$

where n is any whole, positive number greater than 2; μ is an arbitrary, positive constant; λ is the imaginary, frequency parameter; ω_1 is the cut-off frequency; and $\omega_{\alpha,1}$ etc. are arbitrary resonant and anti-resonant frequency parameters in the attenuation band.

15 10. A four-terminal, low-pass, filter network of image-impedance class α_{2n} or α_{2n}^* having frequency characteristics z_1 and z_2 , where

20 equals

$$\log \mu \frac{(\lambda^2 + \omega_{\alpha,1}^2)(\lambda^2 + \omega_{\alpha,3}^2) \cdots (\lambda^2 + \omega_{\alpha,2n-1}^2)}{\sqrt{\lambda^2 + \omega_1^2}(\lambda^2 + \omega_{\alpha,2}^2) \cdots (\lambda^2 + \omega_{\alpha,2n-2}^2)}$$

25

where n is any whole, positive number greater than unity; μ is an arbitrary, positive constant; λ is the imaginary, frequency parameter; ω_1 is the cut-off frequency; and $\omega_{\alpha,1}$ etc. are arbitrary resonant and anti-resonant frequency parameters in the attenuation band.

11. A symmetrical, four-terminal network comprising four branches connected in the form of a lattice, each branch having a condenser and two coils in series, the coils of the branches being correspondingly disposed, four corresponding coils being tightly coupled in two pairs, the other four corresponding coils being also tightly coupled in pairs, two additional coils each tightly coupled to one of the last-named pairs, and two condensers each connected with one of the two additional coils.

45 12. A four-terminal, image-impedance filter network with more than two bands of free transmission having an image-impedance, frequency-characteristic curve that, in the most favorable case, is intersected by a parallel to the frequency axis of coordinates in at least five points in every transmitting band.

13. In a wave transmission network comprising a plurality of impedances, two impedances adapted to determine the transmission characteristics of the network, said impedances each having a plurality of frequency parameters defining resonances and anti-resonances and being proportioned to provide a free transmission band or free transmission bands and attenuation at frequencies outside the transmission band or bands, said frequency parameters being spaced in the attenuation range or ranges remote from the band limit or band limits on a progressively closer scale near to the band limit to provide a substantially uniform characteristic image impedance throughout the band or bands.

14. A network as defined in claim 1 where m , ω_{α} and ω_a are all Tschebyscheff parameters.

70 15. A four-terminal band-pass, filter network having frequency characteristics z_1 and z_2 where

equals

$$\log m \frac{\sqrt{\lambda^2 + \omega_{-1}^2}(\lambda^2 + \omega_a^2)}{(\lambda^2 + \omega_{\alpha}^2)\sqrt{\lambda^2 + \omega_1^2}}$$

5

were m is a positive constant; λ is the imaginary, frequency parameter; ω_{-1} and ω_1 are cut-off frequencies; and ω_{α} and ω_a are resonant and anti-resonant frequency parameters in the transmission band, m , ω_{α} and ω_a all being Tschebyscheff parameters.

10

16. A network as defined in claim 2 where m , $\omega_{\alpha,1}$, $\omega_{\alpha,2}$ etc. are all Tschebyscheff parameters.

17. A four-terminal, band-pass, filter network 15 of attenuation class $2n-1$ or $2n-1^*$ having frequency characteristics z_1 and z_2 where

$$\log \sqrt{\frac{z_2}{z_1}}$$

20

equals

$$\log m \frac{\sqrt{\lambda^2 + \omega_{-1}^2}(\lambda^2 + \omega_{\alpha,2}^2)(\lambda^2 + \omega_{\alpha,3}^2) \cdots (\lambda^2 + \omega_{\alpha,2n-2}^2)}{(\lambda^2 + \omega_{\alpha,1}^2)(\lambda^2 + \omega_{\alpha,3}^2) \cdots (\lambda^2 + \omega_{\alpha,2n-3}^2)\sqrt{\lambda^2 + \omega_1^2}}$$

25

where n is any whole, positive number greater than 2; m is a positive constant; λ is the imaginary, frequency parameter; ω_{-1} and ω_1 are cut-off frequencies; and $\omega_{\alpha,1}$ etc. are resonant and anti-resonant frequency parameters in the transmission band, m , $\omega_{\alpha,1}$ etc., all being Tschebyscheff parameters.

30

18. A network as defined in claim 3 where m , ω_{α} etc. are all Tschebyscheff parameters where n is, however, any whole number greater than 1.

35

19. A four-terminal band-pass, filter of attenuation class $2n$ or $2n^*$ having frequency characteristics z_1 and z_2 , where

$$\log \sqrt{\frac{z_2}{z_1}}$$

40

equals

$$\log m \frac{(\lambda^2 + \omega_{\alpha,1}^2)(\lambda^2 + \omega_{\alpha,3}^2) \cdots (\lambda^2 + \omega_{\alpha,2n-1}^2)}{\sqrt{\lambda^2 + \omega_{-1}^2}(\lambda^2 + \omega_{\alpha,2}^2) \cdots (\lambda^2 + \omega_{\alpha,2n-2}^2)\sqrt{\lambda^2 + \omega_1^2}}$$

45

where n is any whole, positive number greater than 1; m is a positive constant; λ is the imaginary, frequency parameter; ω_{-1} and ω_1 are cut-off frequencies; and $\omega_{\alpha,1}$ etc. are resonant and anti-resonant frequency parameters in the transmission band, m , $\omega_{\alpha,1}$ etc. all being Tschebyscheff parameters.

50

20. A network as defined in claim 4, where μ , ω_{α} and ω_a are all Tschebyscheff parameters.

55

21. A four-terminal, low-and-high-pass, filter network having frequency characteristics z_1 and z_2 , where

$$\log \sqrt{\frac{z_2}{z_1}}$$

60

equals

$$\log \mu \frac{\lambda \sqrt{\lambda^2 + \omega_{-1}^2}(\lambda^2 + \omega_a^2)}{(\lambda^2 + \omega_{\alpha}^2)\sqrt{\lambda^2 + \omega_1^2}}$$

65

where μ is a positive constant; λ is the imaginary, frequency parameter; ω_{-1} and ω_1 are cut-off frequencies; and ω_{α} and ω_a are resonant and anti-resonant frequency parameters in the transmission bands, μ , ω_{α} , ω_a , all being Tschebyscheff parameters.

70

22. A network as defined in claim 5 where μ , ω_{α} , ω_{-1} etc., are all Tschebyscheff parameters.

75

23. A four-terminal, low-and-high-pass, filter 75

75

$$\log \sqrt{\frac{z_2}{z_1}}$$

network of attenuation class a_{2n-1} or a_{2n-1}^* having frequency characteristics z_1 and z_2 , where

5 equals

$$\log \mu \frac{(\lambda^2 + \omega_{\alpha, n-1}^2) \cdots (\lambda^2 + \omega_{\alpha, 2}^2) \sqrt{\lambda^2 + \omega_{\alpha, 1}^2} (\lambda^2 + \omega_{\alpha, 1}^2) \cdots (\lambda^2 + \omega_{\alpha, n-2}^2)}{\lambda (\lambda^2 + \omega_{\alpha, n-2}^2) \cdots (\lambda^2 + \omega_{\alpha, 2}^2) \sqrt{\lambda^2 + \omega_{\alpha, 1}^2} (\lambda^2 + \omega_{\alpha, 1}^2) \cdots (\lambda^2 + \omega_{\alpha, n-1}^2)}$$

10 where $v=n$ for n odd; $v=n+1$, $\omega_{\alpha, n}=0$ and the last factor of the denominator is omitted for n even; n is any whole, positive number greater than 1; μ is a positive constant; λ is the imaginary, frequency parameter; $\omega_{\alpha, 1}$ and $\omega_{\alpha, 1}$ are cut-off frequencies; and $\omega_{\alpha, n-1}$ etc. are resonant and anti-resonant frequency parameters in the transmission bands, μ , $\omega_{\alpha, n-1}$ etc. all being Tschebyscheff parameters.

20 24. A network as defined in claim 6 where $\mu, \omega_{\alpha, n-1}$ etc. are all Tschebyscheff parameters, where n is, however, any whole number greater than 1.

25 25. A four-terminal, low-and-high-pass, filter network of attenuation class a_{2n} or a_{2n}^* having frequency characteristics z_1 and z_2 , where

30 equals

$$\log \mu \frac{\lambda (\lambda^2 + \omega_{\alpha, n-2}^2) \cdots (\lambda^2 + \omega_{\alpha, 2}^2) (\lambda^2 + \omega_{\alpha, 1}^2) \cdots (\lambda^2 + \omega_{\alpha, n-2}^2)}{(\lambda^2 + \omega_{\alpha, n-1}^2) \cdots (\lambda^2 + \omega_{\alpha, 2}^2) \sqrt{\lambda^2 + \omega_{\alpha, 1}^2} (\gamma + \omega_{\alpha, 1}^2) (\lambda^2 + \omega_{\alpha, 1}^2) \cdots (\lambda^2 + \omega_{\alpha, n-1}^2)}$$

35 where $v=n$ for n odd; $v=n+1$, $\omega_{\alpha, n}=0$ and the last factor of the denominator is omitted for n even; n is any whole, positive number greater than 1; μ is a positive constant; λ is the imaginary, frequency parameter; $\omega_{\alpha, 1}$ and $\omega_{\alpha, 1}$ are cut-off frequencies; and $\omega_{\alpha, n-1}$ etc. are resonant and anti-resonant frequency parameters in the transmission bands, μ , $\omega_{\alpha, n-1}$ etc. all being Tschebyscheff parameters.

40 26. A network as defined in claim 7 where $m, \omega_{\alpha, n-2}$ etc. are all Tschebyscheff parameters, where n is, however, any whole positive number greater than unity.

45 27. A four-terminal, low-pass, filter network of attenuation class $2n-1$ or $2n-1^*$ having frequency characteristics z_1 and z_2 , where

50 equals

$$\log m \frac{\lambda (\lambda^2 + \omega_{\alpha, n-3}^2) \cdots (\lambda^2 + \omega_{\alpha, 1}^2)}{(\lambda^2 + \omega_{\alpha, n-2}^2) \cdots (\lambda^2 + \omega_{\alpha, 2}^2) \sqrt{\lambda^2 + \omega_{\alpha, 1}^2}}$$

55 where n is any whole, positive number greater than unity; m is a positive constant; λ is the imaginary, frequency parameter; $\omega_{\alpha, 1}$ is the cut-off frequency; and $\omega_{\alpha, n-2}$ etc. are resonant and anti-resonant frequency parameters in the transmission band, m , $\omega_{\alpha, n-2}$ etc. all being Tschebyscheff parameters.

60 28. A network as defined in claim 8 where n is, however, any whole positive number and where $m, \omega_{\alpha, n-1}$ etc. are all Tschebyscheff parameters.

65 29. A four-terminal, low-pass, filter network of attenuation class $2n$ or $2n^*$ having frequency characteristics z_1 and z_2 , where

70 equals

$$\log m \frac{(\lambda^2 + \omega_{\alpha, n-1}^2) (\lambda^2 + \omega_{\alpha, n-3}^2) \cdots (\lambda^2 + \omega_{\alpha, 1}^2)}{\lambda (\lambda^2 + \omega_{\alpha, n-2}^2) \cdots (\lambda^2 + \omega_{\alpha, 2}^2) \sqrt{\lambda^2 + \omega_{\alpha, 1}^2}}$$

75 where n is any whole, positive number; m is a pos-

itive constant; λ is the imaginary, frequency parameter; $\omega_{\alpha, 1}$ is the cut-off frequency; and $\omega_{\alpha, n-1}$ etc. are resonant and anti-resonant frequency parameters in the transmission band, $m, \omega_{\alpha, n-1}$ etc. all being Tschebyscheff parameters.

30. A network as defined in claim 9 where

10 $\mu, \omega_{\alpha, 1}$ etc. are all Tschebyscheff parameters, where n is, however, any whole positive number greater than unity.

15 31. A four-terminal, high-pass, filter network of attenuation class a_{2n-1} or a_{2n-1}^* having frequency characteristics z_1 and z_2 , where

$$\log \mu \sqrt{\frac{z_2}{z_1}}$$

equals

$$\log \mu \frac{(\lambda^2 + \omega_{\alpha, 1}^2) \cdots (\lambda^2 + \omega_{\alpha, n-3}^2)}{\sqrt{\lambda^2 + \omega_{\alpha, 1}^2} (\lambda^2 + \omega_{\alpha, 1}^2) \cdots (\lambda^2 + \omega_{\alpha, n-2}^2)}$$

20 where n is any whole, positive number greater than unity; μ is a positive constant; λ is the imaginary, frequency parameter; $\omega_{\alpha, 1}$ is the cut-off frequency; and $\omega_{\alpha, 1}$ etc. are resonant and anti-resonant frequency parameters in the transmission band, $\mu, \omega_{\alpha, 1}$ etc. all being Tschebyscheff parameters.

25 32. A network as defined in claim 10 where n is, however, any whole positive number and where $\mu, \omega_{\alpha, 1}$ etc. are all Tschebyscheff parameters.

30 33. A four-terminal, high-pass, filter network of attenuation class a_{2n} or a_{2n}^* having frequency characteristics z_1 and z_2 , where

$$\log \mu \sqrt{\frac{z_2}{z_1}}$$

equals

$$\log \mu \frac{(\lambda^2 + \omega_{\alpha, 1}^2) (\lambda^2 + \omega_{\alpha, 3}^2) \cdots (\lambda^2 + \omega_{\alpha, n-1}^2)}{\sqrt{\lambda^2 + \omega_{\alpha, 1}^2} (\lambda^2 + \omega_{\alpha, 1}^2) \cdots (\lambda^2 + \omega_{\alpha, n-2}^2)}$$

35 where n is any whole, positive number; μ is a positive constant; λ is the imaginary, frequency parameter; $\omega_{\alpha, 1}$ is the cut-off frequency; and $\omega_{\alpha, 1}$ etc. are arbitrary resonant and anti-resonant frequency parameters in the transmission band, $\mu, \omega_{\alpha, 1}$ etc. all being Tschebyscheff parameters.

40 34. A four-terminal, image-impedance, filter network with two attenuation and two transmission bands, having an image impedance, frequency-characteristic curve that, in the most favorable case, is intersected by a parallel to the frequency axis of coordinates in at least five points in every transmitting band.

45 35. A four-terminal, band-pass, filter network having an image-impedance, frequency-characteristic curve that, in the most favorable case, is intersected by a parallel to the frequency axis of coordinates in at least five points in the transmitting band.

50 36. A four-terminal, low-pass, filter network having an image-impedance, frequency-characteristic curve that, in the most favorable case, is intersected by a parallel to the frequency axis of coordinates in at least four points in the transmitting band.

55 37. A four-terminal, high-pass, filter network having an image-impedance, frequency-characteristic curve that, in the most favorable case, is intersected by a parallel to the frequency axis of coordinates in at least four points in the transmitting band.

38. A four-terminal, low-and-high-pass, filter network having an image-impedance, frequency-characteristic curve that, in the most favorable case, is intersected by a parallel to the frequency axis of coordinates in at least five points in the transmitting band, one of which five points may be at infinity.

39. An electrical filter circuit in the form of a four-terminal network having two input and two output terminals which satisfies one or both of the conditions, firstly that the various minima of attenuation occurring approximately at such normalized frequencies which are equal to the ratio between the normalized limits of the Tschebyscheffian intervals and the normalized resonance and antiresonance frequencies of the attenuation function, over a prescribed part or parts of the attenuation region are substantially equal, and secondly that the various maxima and minima of surge impedance occurring approximately at such normalized frequencies which are equal to the ratio between the normalized limits of the Tschebyscheffian intervals and the normalized resonance and antiresonance frequencies of the surge impedance function, over a prescribed part or parts of the pass region all deviate to substantially the same extent from a predetermined value.

40. A low-and-high-pass, filter network of image-impedance class $2n-1$ or $2n-1^*$ having frequency characteristics z_1 and z_2 , where

$$\log m \frac{\sqrt{\lambda^2 + \omega_{-1}^2}(\lambda^2 + \omega_{a,2}^2)(\lambda^2 + \omega_{a,n}^2) \cdots (\lambda^2 + \omega_{a,2n-2}^2)}{(\lambda^2 + \omega_{a,1}^2)(\lambda^2 + \omega_{a,3}^2) \cdots (\lambda^2 + \omega_{a,2n-3}^2) \sqrt{\lambda^2 + \omega_1^2}}$$

where n is any whole, positive number greater than 1; m is an arbitrary, positive constant; λ is the imaginary, frequency parameter; ω_{-1} and ω_1 are cut-off frequencies; and $\omega_{a,1}$ etc. are arbitrary resonant and anti-resonant frequency parameters in the attenuation band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

41. A band-pass, filter network of attenuation class $2n-1$ or $2n-1^*$ having frequency characteristics z_1 and z_2 where

$$\log m \frac{\sqrt{\lambda^2 + \omega_{-1}^2}(\lambda^2 + \omega_{a,2}^2)(\lambda^2 + \omega_{a,4}^2) \cdots (\lambda^2 + \omega_{a,2n-2}^2)}{(\lambda^2 + \omega_{a,1}^2)(\lambda^2 + \omega_{a,3}^2) \cdots (\lambda^2 + \omega_{a,2n-3}^2) \sqrt{\lambda^2 + \omega_1^2}}$$

where n is any whole, positive number greater than 1; m is a positive constant; λ is the imaginary, frequency parameter; ω_{-1} and ω_1 are cut-

off frequencies; and $\omega_{a,1}$ etc. are resonant and anti-resonant frequency parameters in the trans-

mission band, the filter network comprising a

first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

42. A low-and-high-pass, filter network of image-impedance class $2n$ or $2n^*$ having frequency characteristics z_1 and z_2 where

$$\log \sqrt{z_1 z_2} \text{ equals}$$

$$\log m \frac{(\lambda^2 + \omega_{a,1}^2)(\lambda^2 + \omega_{a,3}^2) \cdots (\lambda^2 + \omega_{a,2n-1}^2)}{\sqrt{\lambda^2 + \omega_{-1}^2}(\lambda^2 + \omega_{a,2}^2) \cdots (\lambda^2 + \omega_{a,2n-2}^2) \sqrt{\lambda^2 + \omega_1^2}}$$

where n is any whole, positive number; m is an arbitrary, positive constant; λ is the imaginary, frequency parameter; ω_{-1} and ω_1 are cut-off frequencies; and $\omega_{a,1}$ etc. are arbitrary resonant and anti-resonant frequency parameters in the attenuation band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

43. A band-pass, filter of attenuation class $2n$ or $2n^*$ having frequency characteristics z_1 and z_2 where

$$\log \sqrt{\frac{z_2}{z_1}} \text{ equals}$$

$$\log m \frac{(\lambda^2 + \omega_{a,1}^2)(\lambda^2 + \omega_{a,3}^2) \cdots (\lambda^2 + \omega_{a,2n-1}^2)}{\sqrt{\lambda^2 + \omega_{-1}^2}(\lambda^2 + \omega_{a,2}^2) \cdots (\lambda^2 + \omega_{a,2n-2}^2) \sqrt{\lambda^2 + \omega_1^2}}$$

where n is any whole, positive number; m is an arbitrary, positive constant; λ is the imaginary, frequency parameter; ω_{-1} and ω_1 are cut-off frequencies; and $\omega_{a,1}$ etc. are resonant and anti-resonant frequency parameters in the transmission band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

44. A band-pass, filter network of image-impedance class a_{2n-1} or a_{2n-1}^* having frequency characteristics z_1 and z_2 , where

$$\log \sqrt{z_1 z_2} \text{ equals}$$

$$\log m \frac{(\lambda^2 + \omega_{-1}^2) \sqrt{\lambda^2 + \omega_{-1}^2} (\lambda^2 + \omega_{a,1}^2) \cdots (\lambda^2 + \omega_{a,v-1}^2)}{(\lambda^2 + \omega_{a,1}^2) \sqrt{\lambda^2 + \omega_1^2} (\lambda^2 + \omega_{a,2}^2) \cdots (\lambda^2 + \omega_{a,v-1}^2)}$$

where $v=n$ for n odd; $v=n+1$, $\omega_{-1}=0$, and the last factor of the denominator is omitted for n even; n is any whole, positive number greater

than 1; μ is an arbitrary, positive constant; λ is the imaginary, frequency parameter; ω_{-1} and ω_1 are cut-off frequencies; and $\omega_{-\alpha-1}$, etc., are arbitrary resonant and anti-resonant frequency parameters in the attenuation bands; the filter network comprising a first terminal, a second terminal, a third terminal, and a fourth terminal, a circuit connecting the first and the second terminals, a circuit connecting the third and the

14. *Attenuation class*

$$\left| \log \mu \frac{\lambda(\lambda^2 + \omega_{-\alpha-1}^2) \dots (\lambda^2 + \omega_{-\alpha-n}^2)}{(\lambda^2 + \omega_{-\alpha-1}^2) \dots (\lambda^2 + \omega_{-\alpha-n}^2) \sqrt{(\lambda^2 + \omega_{-1}^2)(\lambda^2 + \omega_1^2)} \dots (\lambda^2 + \omega_{-\alpha-1}^2)} \right|$$

15

fourth terminals the circuits being inductively coupled to one side and to the other side of an intermediate point, and an inductive coupling to one side of the intermediate point being negative relative to an inductive coupling to the other side of the intermediate point.

20

45. A low-and-high-pass, filter network of attenuation class a_{2n-1} or a_{2n-1}^* having frequency characteristics z_1 and z_2 , where

25

15. *Attenuation class*

$$\left| \log \sqrt{\frac{z_2}{z_1}} \right|$$

equals

30

16. *Attenuation class*

$$\left| \log \mu \frac{(\lambda^2 + \omega_{-\alpha-1}^2)(\lambda^2 + \omega_{-\alpha-3}^2) \dots (\lambda^2 + \omega_{-\alpha-n}^2) \sqrt{\lambda^2 + \omega_{-1}^2}(\lambda^2 + \omega_{-3}^2) \dots (\lambda^2 + \omega_{-n-2}^2)}{(\lambda^2 + \omega_{-\alpha-1}^2)(\lambda^2 + \omega_{-\alpha-4}^2) \dots (\lambda^2 + \omega_{-\alpha-n}^2) \sqrt{\lambda^2 + \omega_1^2}(\lambda^2 + \omega_{-2}^2) \dots (\lambda^2 + \omega_{-n-1}^2)} \right|$$

35

where $v=n$ for n odd; $v=n+1$, $\omega_{-\alpha,n}=0$, and the last factor of the denominator is omitted for n even; n is any whole, positive number greater than 1; μ is a positive constant; λ is the imaginary frequency parameter; ω_{-1} and ω_1 are cut-off frequencies; and $\omega_{-\alpha-1}$, etc. are resonant and anti-resonant frequency parameters in the transmission bands; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

40

46. A band-pass, filter network of image-impedance class a_{2n} or a_{2n}^* having frequency characteristics z_1 and z_2 , where

55

17. *Attenuation class*

$$\left| \log \sqrt{z_1 z_2} \right|$$

equals

60

18. *Attenuation class*

$$\left| \log \mu \frac{\lambda(\lambda^2 + \omega_{-\alpha-2}^2) \dots (\lambda^2 + \omega_{-\alpha-1}^2)(\lambda^2 + \omega_{-\alpha-1}^2) \dots (\lambda^2 + \omega_{-\alpha-n}^2)}{(\lambda^2 + \omega_{-\alpha-1}^2) \dots (\lambda^2 + \omega_{-\alpha-n}^2) \sqrt{(\lambda^2 + \omega_{-1}^2)(\lambda^2 + \omega_1^2)} \dots (\lambda^2 + \omega_{-\alpha-1}^2)} \right|$$

65

where $v=n$ for n odd; $v=n+1$, $\omega_{-\alpha,n}=0$, and the last factor of the denominator is omitted for n even; n is any whole, positive number; μ is an arbitrary, positive constant; λ is the imaginary, frequency parameter; ω_{-1} and ω_1 are cut-off frequencies; and $\omega_{-\alpha-1}$, etc. are arbitrary resonant and anti-resonant frequency parameters in the attenuation bands; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

70

49. A low-pass, filter network of attenuation class $2n-1$ or $2n-1^*$ having frequency characteristics z_1 and z_2 where

75

19. *Attenuation class*

$$\left| \log \mu \frac{\lambda(\lambda^2 + \omega_{-1}^2) \dots (\lambda^2 + \omega_{-n}^2)}{(\lambda^2 + \omega_{-1}^2) \dots (\lambda^2 + \omega_{-n}^2) \sqrt{\lambda^2 + \omega_1^2}} \right|$$

tive relative to an inductive coupling to the other side of the intermediate point.

47. A low-and-high-pass, filter network of attenuation class a_{2n} or a_{2n}^* having frequency characteristics z_1 and z_2 , where

$$\left| \log \sqrt{\frac{z_2}{z_1}} \right|$$

equals

where $v=n$ for n odd; $v=n+1$, $\omega_{-\alpha,n}=0$, and the last factor of the denominator is omitted for n even; n is any whole, positive number; μ is a positive constant; λ is the imaginary, frequency parameter; ω_{-1} and ω_1 are cut-off frequencies; and $\omega_{-\alpha-1}$, etc. are resonant and anti-resonant frequency parameters in the transmission bands; the filter network comprising a first terminal, a second terminal, a third terminal, and a fourth terminal, a circuit connecting the first and the second terminals, a circuit connecting the third and the fourth terminals, the circuits being inductively coupled to one side and to the

other side of an intermediate point, and an inductive coupling to one side of the intermediate point being negative relative to an inductive coupling to the other side of the intermediate point.

48. A high-pass, filter network of image-impedance class 2_{n-1} or 2_{n-1}^* having frequency characteristics z_1 and z_2 , where

$$\left| \log \sqrt{z_1 z_2} \right|$$

equals

$$\left| \log m \frac{\lambda(\lambda^2 + \omega_{-1}^2) \dots (\lambda^2 + \omega_{-n}^2)}{(\lambda^2 + \omega_{-1}^2) \dots (\lambda^2 + \omega_{-n}^2) \sqrt{\lambda^2 + \omega_1^2}} \right|$$

where n is any whole positive number; m is an arbitrary, positive constant; λ is the cut-off frequency; and ω_{-1} , etc. are arbitrary resonant and anti-resonant frequency parameters in the attenuation band; the filter network comprising a first terminal, a second terminal, a third terminal, and a fourth terminal, a circuit connecting the first and the second terminals, a circuit connecting the third and the fourth terminals, the circuits being inductively coupled to one side and to the other

other side of an intermediate point, and an inductive coupling to one side of the intermediate point being negative relative to an inductive coupling to the other side of the intermediate point.

49. A low-pass, filter network of attenuation class $2n-1$ or $2n-1^*$ having frequency characteristics z_1 and z_2 where

$$\left| \log \sqrt{\frac{z_2}{z_1}} \right|$$

equals

$$\left| \log m \frac{\lambda(\lambda^2 + \omega_{-1}^2) \dots (\lambda^2 + \omega_{-n}^2)}{(\lambda^2 + \omega_{-1}^2) \dots (\lambda^2 + \omega_{-n}^2) \sqrt{\lambda^2 + \omega_1^2}} \right|$$

where n is any whole positive number; m is a positive constant; λ is the imaginary, frequency

parameter; ω_1 is the cut-off frequency; and $\omega_{a,2n-2}$ etc. are resonant and anti-resonant frequency parameters in the transmission band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

50. A high-pass, filter network of image-impedance class $2n$ or $2n^*$ having frequency characteristics z_1 and z_2 , where

equals

$$20 \quad \left| \log \frac{(\lambda^2 + \omega_{a,2n-1}^2)(\lambda^2 + \omega_{a,2n-3}^2) \cdots (\lambda^2 + \omega_{a,1}^2)}{\lambda(\lambda^2 + \omega_{a,2n-2}^2) \cdots (\lambda^2 + \omega_{a,2}^2)\sqrt{\lambda^2 + \omega_1^2}} \right|$$

where n is any whole, positive number; m is an arbitrary, positive constant; λ is the imaginary, frequency parameter; ω_1 is the cut-off frequency; and $\omega_{a,2n-1}$ etc. are arbitrary resonant and anti-resonant frequency parameters in the attenuation band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

51. A low-pass, filter network of attenuation class $2n$ or $2n^*$ having frequency characteristics z_1 and z_2 , where

equals

$$45 \quad \left| \log \frac{\sqrt{z_2}}{z_1} \right| \quad \left| \log \frac{(\lambda^2 + \omega_{a,2n-1}^2)(\lambda^2 + \omega_{a,2n-3}^2) \cdots (\lambda^2 + \omega_{a,1}^2)}{\lambda(\lambda^2 + \omega_{a,2n-2}^2) \cdots (\lambda^2 + \omega_{a,2}^2)\sqrt{\lambda^2 + \omega_1^2}} \right|$$

where n is any whole positive number; m is a positive constant; λ is the imaginary, frequency parameter; ω_1 is the cut-off frequency; and $\omega_{a,2n-1}$ etc. are resonant and anti-resonant frequency parameters in the transmission band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

52. A low-pass, filter network of image-impedance class α_{2n-1} or α_{2n-1}^* having frequency characteristics z_1 and z_2 , where

equals

$$70 \quad \left| \log \frac{(\lambda^2 + \omega_{a,1}^2) \cdots (\lambda^2 + \omega_{a,2n-3}^2)}{\sqrt{\lambda^2 + \omega_1^2}(\lambda^2 + \omega_{a,2}^2) \cdots (\lambda^2 + \omega_{a,2n-2}^2)} \right|$$

where n is any whole, positive number; μ is an arbitrary, positive constant; λ is the imaginary, frequency parameter; ω_1 is the cut-off frequency; and $\omega_{a,1}$ etc. are arbitrary resonant and anti-

resonant frequency parameters in the attenuation band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

53. A high-pass, filter network of attenuation class α_{2n-1} or α_{2n-1}^* having frequency characteristics z_1 and z_2 , where

$$\left| \log \sqrt{\frac{z_2}{z_1}} \right|$$

equals

$$20 \quad \left| \log \mu \frac{(\lambda^2 + \omega_{a,1}^2) \cdots (\lambda^2 + \omega_{a,2n-3}^2)}{\sqrt{\lambda^2 + \omega_1^2}(\lambda^2 + \omega_{a,2}^2) \cdots (\lambda^2 + \omega_{a,2n-2}^2)} \right|$$

where n is any whole, positive number; μ is an arbitrary positive constant; λ is the imaginary, frequency parameter; ω_1 is the cut-off frequency; and $\omega_{a,1}$ etc. are arbitrary resonant and anti-resonant frequency parameters in the transmission band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

54. A low-pass, filter network of image-impedance class α_{2n} or α_{2n}^* having frequency characteristics z_1 and z_2 , where

$$\left| \log \sqrt{z_1 z_2} \right|$$

equals

$$45 \quad \left| \log \mu \frac{(\lambda^2 + \omega_{a,1}^2)(\lambda^2 + \omega_{a,3}^2) \cdots (\lambda^2 + \omega_{a,2n-1}^2)}{\sqrt{\lambda^2 + \omega_1^2}(\lambda^2 + \omega_{a,2}^2) \cdots (\lambda^2 + \omega_{a,2n-2}^2)} \right|$$

where n is any, whole positive number; μ is an arbitrary, positive constant; λ is the imaginary, frequency parameter; ω_1 is the cut-off frequency; and $\omega_{a,1}$ etc. are arbitrary resonant and anti-resonant frequency parameters in the attenuation band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

55. A high-pass, filter network of attenuation class α_{2n} or α_{2n}^* having frequency characteristics z_1 and z_2 , where

$$\left| \log \sqrt{\frac{z_2}{z_1}} \right|$$

equals

$$70 \quad \left| \log \mu \frac{(\lambda^2 + \omega_{a,1}^2)(\lambda^2 + \omega_{a,3}^2) \cdots (\lambda^2 + \omega_{a,2n-1}^2)}{\sqrt{\lambda^2 + \omega_1^2}(\lambda^2 + \omega_{a,2}^2) \cdots (\lambda^2 + \omega_{a,2n-2}^2)} \right|$$

where n is any whole, positive number; μ is a positive constant; λ is the imaginary, frequency

- parameter; ω_1 is the cut-off frequency; and $\omega_{a,1}$ etc. are arbitrary resonant and anti-resonant frequency parameters in the transmission band; the filter network comprising a first terminal, a second terminal, a third terminal, and a fourth terminal, a circuit connecting the first and the second terminals, a circuit connecting the third and the fourth terminals, the circuits being inductively coupled to one side and to the other side of an intermediate point, and an inductive coupling to one side of the intermediate point being negative relative to an inductive coupling to the other side of the intermediate point.

56. A four-terminal, low-and-high pass, filter network of image-impedance class $2n-1$ or $2n-1^*$ having frequency characteristics z_1 and z_2 , where

$$|\log \sqrt{z_1 z_2}|$$

20. equals

$$\log m \frac{\sqrt{\lambda^2 + \omega_{-1}^2} (\lambda^2 + \omega_{a,2}^2) (\lambda^2 + \omega_{a,4}^2) \dots (\lambda^2 + \omega_{a,2n-2}^2)}{(\lambda^2 + \omega_{a,1}^2) (\lambda^2 + \omega_{a,3}^2) \dots (\lambda^2 + \omega_{a,2n-3}^2) \sqrt{\lambda^2 + \omega_1^2}}$$

25. where n is any whole, positive number greater than 1; m is an arbitrary, positive constant; λ is the imaginary, frequency parameter; ω_{-1} and ω_1 are cut-off frequencies; and $\omega_{a,1}$ etc. are arbitrary resonant and anti-resonant frequency parameters in the transmission band; the filter network having three or more coils mutually inductively related

30. and no two of the coils having an essential, direct, galvanical connection.

35. 57. A four-terminal, band-pass, filter network of attenuation class $2n-1$ or $2n-1^*$ having frequency characteristics z_1 and z_2 , where

$$|\log \sqrt{\frac{z_1}{z_2}}|$$

40. equals

$$\log m \frac{\sqrt{\lambda^2 + \omega_{-1}^2} (\lambda^2 + \omega_{a,2}^2) (\lambda^2 + \omega_{a,4}^2) \dots (\lambda^2 + \omega_{a,2n-2}^2)^2}{(\lambda^2 + \omega_{a,1}^2) (\lambda^2 + \omega_{a,3}^2) \dots (\lambda^2 + \omega_{a,2n-3}^2) \sqrt{\lambda^2 + \omega_1^2}}$$

45. where n is any whole, positive number greater than 1; m is a positive constant; λ is the imaginary, frequency parameter; ω_{-1} and ω_1 are cut-off frequencies; and $\omega_{a,1}$ etc. are resonant and anti-resonant frequency parameters in the transmission band; the filter network having three or more coils mutually inductively related together, and no two of the coils having an essential, direct, galvanical connection.

50. 60. 58. A four-terminal, low-and-high-pass, filter network of image-impedance class $2n$ or $2n^*$ having frequency characteristics z_1 and z_2 , where

$$|\log \sqrt{z_1 z_2}|$$

65. equals

$$\log m \frac{(\lambda^2 + \omega_{a,1}^2) (\lambda^2 + \omega_{a,3}^2) \dots (\lambda^2 + \omega_{a,2n-1}^2)}{\sqrt{\lambda^2 + \omega_{-1}^2} (\lambda^2 + \omega_{a,2}^2) \dots (\lambda^2 + \omega_{a,2n-2}^2) \sqrt{\lambda^2 + \omega_1^2}}$$

70. where n is any whole, positive number; m is an arbitrary, positive constant; λ is the imaginary, frequency parameter; ω_{-1} and ω_1 are cut-off fre-

quencies; and $\omega_{a,1}$ etc. are arbitrary resonant and anti-resonant frequency parameters in the attenuation band; the filter network having three or more coils mutually inductively related together, and no two of the coils having an essential, direct, galvanical connection.

75. 59. A four-terminal, band-pass, filter of attenuation class $2n$ or $2n^*$ having frequency characteristics z_1 and z_2 , where

$$\log m \frac{\sqrt{\lambda^2 + \omega_{-1}^2} (\lambda^2 + \omega_{a,2}^2) \dots (\lambda^2 + \omega_{a,2n-2}^2)}{(\lambda^2 + \omega_{a,1}^2) (\lambda^2 + \omega_{a,3}^2) \dots (\lambda^2 + \omega_{a,2n-3}^2) \sqrt{\lambda^2 + \omega_1^2}}$$

80. where n is any whole, positive number; m is an arbitrary, positive constant; λ is the imaginary, frequency parameter; ω_{-1} and ω_1 are cut-off frequencies; and $\omega_{a,1}$ etc. are resonant and anti-resonant frequency parameters in the transmission band; the filter network having three or more coils mutually inductively related together, and no two of the coils having an essential, direct, galvanical connection.

85. 60. A four-terminal, band-pass, filter network of image-impedance class $2n-1$ or $2n-1^*$ having frequency characteristics z_1 and z_2 , where

$$|\log \sqrt{z_1 z_2}|$$

90. equals

$$\dots (\lambda^2 + \omega_{a,n}^2) \sqrt{\lambda^2 + \omega_{-1}^2} (\lambda^2 + \omega_{a,1}^2) \dots (\lambda^2 + \omega_{a,n-1}^2) \dots (\lambda^2 + \omega_{a,2}^2) \sqrt{\lambda^2 + \omega_1^2} (\lambda^2 + \omega_{a,3}^2) \dots (\lambda^2 + \omega_{a,n-2}^2)$$

95. where $v=n$ for n odd; $v=n+1$, $\omega_{a,n}=0$ and the last factor of the denominator is omitted for n even; n is any whole, positive number greater than 1; μ is an arbitrary, positive constant; λ is the imaginary, frequency parameter; ω_{-1} and ω_1 are cut-off frequencies; and $\omega_{a,1}$ etc. are arbitrary resonant and anti-resonant frequency parameters in the attenuation bands; the filter network having three or more coils mutually in-

of image-impedance class a_{2n} or a_{2n}^* having frequency characteristics z_1 and z_2 , where

5 equals

$$|\log \mu \frac{\lambda(\lambda^2 + \omega_{\alpha,n-2}^2) \dots (\lambda^2 + \omega_{\alpha,2}^2)(\lambda^2 + \omega_{\alpha,1}^2) \dots (\lambda^2 + \omega_{\alpha,n-2}^2)}{(\lambda^2 + \omega_{\alpha,n-1}^2) \dots (\lambda^2 + \omega_{\alpha,2}^2)\sqrt{(\lambda^2 + \omega_{\alpha,1}^2)(\lambda^2 + \omega_{\alpha,2}^2) \dots (\lambda^2 + \omega_{\alpha,n-2}^2)}}|$$

10 where $v=n$ for n odd; $v=n+1$, $\omega_{\alpha,n}=0$, and the last factor of the denominator is omitted for n even; n is any whole, positive number; μ is an arbitrary, positive constant; λ is the imaginary, frequency parameter; ω_1 and ω_2 are cut-off frequencies; and $\omega_{\alpha,1}$ etc. are arbitrary resonant and anti-resonant frequency parameters in the attenuation bands; the filter network having three or more coils mutually inductively related together, and no two of the coils having an essential, direct, galvanical connection.

15 63. A four-terminal, low-and-high-pass, filter network of attenuation class a_{2n} or a_{2n}^* having frequency characteristics z_1 and z_2 , where

$$|\log \sqrt{\frac{z_2}{z_1}}|$$

20 equals

$$|\log \mu \frac{\lambda(\lambda^2 + \omega_{\alpha,n-2}^2) \dots (\lambda^2 + \omega_{\alpha,2}^2)(\lambda^2 + \omega_{\alpha,1}^2) \dots (\lambda^2 + \omega_{\alpha,n-2}^2)}{(\lambda^2 + \omega_{\alpha,n-1}^2) \dots (\lambda^2 + \omega_{\alpha,2}^2)\sqrt{(\lambda^2 + \omega_{\alpha,1}^2)(\lambda^2 + \omega_{\alpha,2}^2) \dots (\lambda^2 + \omega_{\alpha,n-2}^2)}}|$$

25 30 where $v=n$ for n odd; $v=n+1$, $\omega_{\alpha,n}=0$, and the last factor of the denominator is omitted for n even; n is any whole, positive number; μ is a positive constant; λ is the imaginary, frequency parameter; ω_1 and ω_2 are cut-off frequencies; and $\omega_{\alpha,1}$ etc., are resonant and anti-resonant frequency parameters in the transmission bands; the filter network having three or more coils mutually inductively related together, and no two of the coils having an essential, direct, galvanical connection.

35 64. A four-terminal, high-pass, filter network of image-impedance class $2n-1$ or $2n-1^*$ having frequency characteristics z_1 and z_2 where

$$|\log \sqrt{z_1 z_2}|$$

40 equals

$$|\log m \frac{\lambda(\lambda^2 + \omega_{a,2n-3}^2) \dots (\lambda^2 + \omega_{a,1}^2)}{(\lambda^2 + \omega_{a,2n-2}^2) \dots (\lambda^2 + \omega_{a,2}^2)\sqrt{\lambda^2 + \omega_1^2}}|$$

45 50 where n is any whole positive number; m is an arbitrary, positive constant; λ is the imaginary, frequency parameter; ω_1 is the cut-off frequency; and $\omega_{a,2n-2}$ etc. are arbitrary resonant and anti-resonant frequency parameters in the attenuation band; the filter network having three or more coils mutually inductively related together, and no two of the coils having an essential, direct, galvanical connection.

55 60 65. A four-terminal, low-pass, filter network of attenuation class $2n-1$ or $2n-1^*$ having frequency characteristics z_1 and z_2 , where

$$|\log \sqrt{\frac{z_2}{z_1}}|$$

65 equals

$$|\log m \frac{\lambda(\lambda^2 + \omega_{a,2n-3}^2) \dots (\lambda^2 + \omega_{a,1}^2)}{(\lambda^2 + \omega_{a,2n-2}^2) \dots (\lambda^2 + \omega_{a,2}^2)\sqrt{\lambda^2 + \omega_1^2}}|$$

70 75 where n is any whole positive number; m is a positive constant; λ is the imaginary, frequency parameter; ω_1 is the cut-off frequency; and $\omega_{a,2n-2}$ etc. are resonant and anti-resonant frequency parameters in the transmission band; the filter network having three or more coils mutually in-

ductively related together, and no two of the coils having an essential, direct, galvanical connection.

66. A four-terminal, high-pass, filter network

5

10 of image-impedance class $2n$ or $2n^*$ having frequency characteristics z_1 and z_2 , where

$$|\log \sqrt{z_1 z_2}|$$

15 equals

$$|\log m \frac{(\lambda^2 + \omega_{a,2n-1}^2)(\lambda^2 + \omega_{a,2n-3}^2) \dots (\lambda^2 + \omega_{a,1}^2)}{\lambda(\lambda^2 + \omega_{a,2n-2}^2) \dots (\lambda^2 + \omega_{a,2}^2)\sqrt{\lambda^2 + \omega_1^2}}|$$

20 25 where n is any whole, positive number; m is an arbitrary, positive constant; λ is the imaginary, frequency parameter; ω_1 is the cut-off frequency; and $\omega_{a,2n-1}$ etc. are arbitrary resonant and anti-resonant frequency parameters in the attenuation band; the filter network having three or more coils mutually inductively related together, and no two of the coils having an essential, direct, galvanical connection.

30 35 67. A four-terminal, low-pass, filter network of attenuation class $2n$ or $2n^*$ having frequency characteristics z_1 and z_2 , where

$$|\log \sqrt{\frac{z_2}{z_1}}|$$

40 equals

$$|\log m \frac{(\lambda^2 + \omega_{a,2n-1}^2)(\lambda^2 + \omega_{a,2n-3}^2) \dots (\lambda^2 + \omega_{a,1}^2)}{\lambda(\lambda^2 + \omega_{a,2n-2}^2) \dots (\lambda^2 + \omega_{a,2}^2)\sqrt{\lambda^2 + \omega_1^2}}|$$

45 50 where n is any whole positive number; m is a positive constant; λ is the imaginary, frequency parameter; ω_1 is the cut-off frequency; and $\omega_{a,2n-1}$ etc. are resonant and anti-resonant frequency parameters in the transmission band; the filter network having three or more coils mutually inductively related together, and no two of the coils having an essential, direct, galvanical connection.

55 60 65 68. A four-terminal, low-pass, filter network of image-impedance class a_{2n-1} or a_{2n-1}^* having frequency characteristics z_1 and z_2 , where

$$|\log \sqrt{z_1 z_2}|$$

70 equals

$$|\log \mu \frac{(\lambda^2 + \omega_{a,1}^2) \dots (\lambda^2 + \omega_{a,2n-3}^2)}{\sqrt{\lambda^2 + \omega_1^2}(\lambda^2 + \omega_{a,2}^2) \dots (\lambda^2 + \omega_{a,2n-2}^2)}|$$

75 80 where n is any whole, positive number; μ is an arbitrary, positive constant; λ is the imaginary, frequency parameter; ω_1 is the cut-off frequency; and $\omega_{a,1}$ etc. are arbitrary resonant and anti-resonant frequency parameters in the attenuation band; the filter network having three or more coils mutually inductively related together, and no two of the coils having an essential, direct, galvanical connection.

85 90 95 69. A four-terminal, high-pass, filter network of attenuation class a_{2n-1} or a_{2n-1}^* having frequency characteristics z_1 and z_2 , where

$$|\log \sqrt{\frac{z_2}{z_1}}|$$

70 equals

$$|\log \mu \frac{(\lambda^2 + \omega_{a,1}^2) \dots (\lambda^2 + \omega_{a,2n-3}^2)}{\sqrt{\lambda^2 + \omega_1^2}(\lambda^2 + \omega_{a,2}^2) \dots (\lambda^2 + \omega_{a,2n-2}^2)}|$$

75 where n is any whole, positive number; μ is an

arbitrary positive constant; λ is the imaginary frequency parameter; ω_1 is the cut-off frequency; and $\omega_{\alpha,1}$ etc. are arbitrary resonant and anti-resonant frequency parameters in the transmission band; the filter network having three or more coils mutually inductively related together, and no two of the coils having an essential, direct, galvanical connection.

70. A four-terminal, low-pass, filter network of image-impedance class α_{2n} or α_{2n}^* having frequency characteristics z_1 and z_2 , where

$$| \log \sqrt{z_1 z_2} |$$

equals

$$15 \quad | \log \mu \frac{(\lambda^2 + \omega_{\alpha,1}^2)(\lambda^2 + \omega_{\alpha,3}^2) \dots (\lambda^2 + \omega_{\alpha,2n-1}^2)}{\sqrt{\lambda^2 + \omega_1^2}(\lambda^2 + \omega_{\alpha,2}^2) \dots (\lambda^2 + \omega_{\alpha,2n-2}^2)} |$$

where n is any whole, positive number; μ is an arbitrary, positive constant; λ is the imaginary, frequency parameter; ω_1 is the cut-off frequency; and $\omega_{\alpha,1}$ etc. are arbitrary resonant and anti-resonant frequency parameters in the attenuation band; the filter network having three or more coils mutually inductively related together, and no two of the coils having an essential, direct, galvanical connection.

71. A four-terminal, high-pass, filter network of attenuation class α_{2n} or α_{2n}^* having frequency characteristics z_1 and z_2 , where

$$30 \quad | \log \sqrt{\frac{z_2}{z_1}} |$$

equals

$$35 \quad | \log \mu \frac{(\lambda^2 + \omega_{\alpha,1}^2)(\lambda^2 + \omega_{\alpha,3}^2) \dots (\lambda^2 + \omega_{\alpha,2n-1}^2)}{\sqrt{\lambda^2 + \omega_1^2}(\lambda^2 + \omega_{\alpha,2}^2) \dots (\lambda^2 + \omega_{\alpha,2n-2}^2)} |$$

where n is any whole, positive number; μ is a positive constant; λ is the imaginary, frequency parameter; ω_1 is the cut-off frequency; and $\omega_{\alpha,1}$ etc. are arbitrary resonant and anti-

resonant frequency parameters in the transmission band; the filter network having three or more coils mutually inductively related together, and no two of the coils having an essential, direct, galvanical connection.

5

72. In a wave transmission network comprising a plurality of impedances, two impedances adapted to determine the attenuation characteristics of the network, said impedances each having a plurality of frequency parameters defining resonances and antiresonances and being proportioned to provide a free transmission band or free transmission bands and attenuation at frequencies outside the transmission band or bands, said frequency parameters being spaced 15 in the transmission range or ranges remote from the band limit or band limits on a progressively closer scale near to the band limit to provide a substantially uniformly high attenuation characteristic throughout the attenuation band or 20 bands.

25

73. In a wave transmission network comprising a plurality of impedances, two impedances adapted to determine the transmission and attenuation characteristics of the network, said impedances each having a plurality of frequency parameters defining resonances and antiresonances and being proportioned to provide a free transmission band or free transmission bands and attenuation at frequencies outside the transmission band or bands, said frequency parameters being spaced in the attenuation ranges remote from the band limit or band limits on a progressively closer scale near to the band limit to provide a substantially uniform characteristic image impedance and a substantially uniformly high attenuation characteristic throughout the band or bands.
